UNITED STATES PATENT OFFICE

ALBEN E. LUNDELL, OF NEW YORK, AND EDGAR H. CLARK, OF RICHMOND HILL, NEW YORK, ASSIGNORS TO WESTERN ELECTRIC COMPANY, INCORPORATED, OF NEW YORK, N. Y., A CORPORATION OF NEW YORK

TELEPHONE-EXCHANGE SYSTEM

Application filed July 27, 1923. Serial No. 654,106.

This application is a continuation in part of the application of Lundell and Clark, Serial No. 301,891, filed June 5, 1919.

This invention relates to automatic telephone exchange systems and more particularly to semi-automatic telephone systems in which an operator at the central office receives a call manually and extends it through automatic switches.

10 The object of the invention is to provide a controlling equipment at a manual exchange by means of which the automatic selection of a wanted subscriber at a mechanical exchange may be controlled by an operator.

Formerly it was the general practice for the operator at the semi-automatic exchange to assign, by means of a call wire, an idle trunk to the manual operator who, by means 20 of an ordinary cord circuit, extended the connection of a calling subscriber over the assigned trunk to the semi-automatic operator, who in turn by means of an impulse transmitting mechanism and automatic switches completed the connection to the wanted subscriber.

This invention is especially directed towards the provision of an improved central equipment by means of which a manual operator, after receiving the wanted number, automatically selects an idle trunk leading to the exchange in which the wanted subscriber is located, and by means of which the automatic switches at the exchange are 30 controlled to extend the connection to the wanted subscriber's line. The operator connects the selected trunk with the calling subscriber's line by means of an ordinary cord circuit and the control equipment reverts to common use when the connection is completed to the wanted subscriber's line.

It is the purpose of this invention to eliminate the use of a call wire connection between a manual and automatic exchange, 40 and the service of the operator in the automatic exchange in setting up a connection to a subscriber, thus effecting a considerable saving of time for completing a connection and cost of equipment and operators.

50 One feature of this invention is the pro-

vision of a plurality of connecting units to which an idle trunk leading to an automatic exchange, an idle register and controlling equipment and an operator's number selecting equipment may be connected. 55

Another feature is the provision of an indicating device by means of which the number of the selected trunk may be displayed to the operator.

Another feature is the provision of a starting and number selecting equipment by means of which a connecting unit is associated with a calling operator and by means of which the register and controlling equipment may be manipulated to control the 60 selection of the wanted subscriber's number.

Another feature resides in the provision of an allotting equipment whereby an idle connecting unit is assigned for use by a calling operator: in the fact that an individual 70 allotting mechanism is associated with the trunks leading to a particular mechanical exchange; in the accessibility of all allotting mechanism by any operator and in the selective allotting of connecting units to operators where several operators simultaneously connect controlling means to the same allotter.

Another feature resides in the ability of the sender to automatically restore selector 80 switches to their normal position, when they are under the control of said sender, but have not been connected to the wanted line. This condition arises when the operator has set only part of the registers. 85

Another feature resides in the ability of the sender to automatically discharge the apparatus of the connecting link and trunk indicator when that apparatus has been operated and the operator has failed to set 90 any of the registers.

Other features relate to the general organization of the equipment at a manual exchange, the grouping of the various units and the detailed construction of the parts 95 involved in these units which will be set forth in the following description of a preferred embodiment of the invention.

It will be obvious to those skilled in the art that this invention is not limited to the 100

particular type of equipment disclosed, but is applicable to systems employing other well known switching and indicating devices.

Figure 1 illustrates diagrammatically the general outline of an organization at a manual exchange in which a system embodying the various features and equipments of the present invention may be employed. Figures 2 to 9 of the drawings, taken together, illustrate such a system diagrammatically and in detail. The order in which the drawings should be arranged is shown in Figure 10.

In accordance with the present illustration of this invention, the trunks terminating at a manual exchange are divided into groups, each group of trunks leading to a particular mechanical exchange and there connecting with selectively operable switching devices, to be termed incoming selector switches. Each operator at the manual exchange is provided with a set of keys on which the wanted number may be registered, and an indicator for the display of the designation of the mechanical exchange and the trunk chosen for the extension of a call.

There is provided for the common use of all operators a group of connecting units for each of the groups of trunks leading to a mechanical exchange and a group of registering and controlling equipments accessible to all operators through the medium of any one of said connecting units. Each connecting unit consists of three automatic switching mechanisms. One of these mechanisms will be termed an "operator's finder switch" and is provided for the purpose of associating the key-set and indicating equipment of any operator with the connecting unit. A second mechanism that will be termed a "trunk selector" is provided for the purpose of associating the connecting unit with an idle trunk of the group leading to the desired mechanical exchange, and a third mechanism that will be termed a "sender selector" is for the purpose of associating an idle registering and controlling equipment or sender with the connecting unit. All of the senders are accessible to any one of said connecting units.

An allotting and controlling mechanism is provided for each group of connecting units. This mechanism consists of an exchange key for each mechanical exchange at each operator's position, and an allotter switch controlled by the associated exchange keys in any operator's position to allot an idle connecting unit for the use of the operator desiring a connection to the corresponding mechanical exchange.

The manual operator in extending a call to a subscriber in a mechanical exchange makes use of the ordinary manual cord cir-

cuit in combination with one of these connecting units. The operator ascertains the wanted number from the calling subscriber and then associates the keys and the trunk indicator with an idle connecting unit of a group of trunks leading to the desired exchange. The connecting unit is also automatically connected to an idle sender. The finding of an idle trunk leading to the wanted exchange and the indicating of the number of the chosen trunk on the trunk indicator is automatically performed. The operator then proceeds, after having received a dialing tone indicating that an idle sender has been associated with the keys, to manipulate the keys and adjust the sender in accordance with the number wanted. In response to the operation of the digit keys the usual selector switches at the mechanical exchange begin to operate and associate the selected trunk with the wanted subscriber's line. During the operation of the selector switches at the mechanical office, the operator connects the outgoing end of the cord circuit associated with the calling subscriber's line, with the selected trunk, and when the selective operations at the mechanical exchange are completed, the wanted subscriber is signalled in the usual manner and the connecting unit is released and made accessible for a second call.

The selector switches and circuits that may be used in connection with this invention, are well known in the art. Suitable selector switches are shown in Figs. 8 and 9. Their description, however, will not be carried forward with the operating features of this circuit but will be described separately to facilitate a clear understanding of the release features in connection with abandoned calls. A suitable arrangement that may also be used, to operate in conjunction with this circuit, is shown in the Patent No. 1,294,498, to A. E. Lundell, issued Feb. 18, 1919.

Switch mechanism, keyboard and trunk indicator

The switches used in this invention are of the well-known step-by-step type in which a stepping pawl operates a ratchet wheel to which are connected brushes or wipers adapted to travel over the contacts of an arcuate terminal bank. These brushes or wipers are so arranged that for each step of the operating magnet, the brushes or wipers engage a corresponding set of terminals. The operator's finder switch 300, the trunk selector switch 400, and sender selector switch 401 are each equipped with six brushes and corresponding terminal banks, while the allotter switch 121 is provided with two brushes and corresponding terminal banks. These switches have no normal position but stop in whatever position they are

placed by their respective operating magnets.

The switch 510 operates the indicator, in a manner to display the designation of the selected outgoing trunk. This switch is 5 provided with a series of stationary brushes or wipers cooperating with a constantly rotating commutator drum having commutator segments arranged to produce the necessary combinations of impulses in the 10 proper sequence. The commutator segments may be connected to ground or through a resistance to ground.

The keyboard consists of a single row of non-locking keys of the push-button type, 15 and represent the digits 0 to 9. This single row of keys is used for designating the thousands, hundreds, tens and units digits of the wanted number. A separate exchange key and a wipe-out key are also of 20 the non-locking push-button type.

The trunk indicator consists of three series of ordinary switchboard lamps arranged to indicate the hundreds, tens and units digits.

25 *General outline of operation.*

Referring now to Figure 1 a brief description of the organization of the system will be given.

30 Each manual operator's position 100 to 103, is provided with the usual multiple jacks 104 in which manual subscriber's lines terminate. Besides these jacks, there are a number of multiple jacks 105 in which 35 terminate trunks arranged in groups 106, 107, etc., leading to mechanical offices, such as 110, 111, etc. Cord circuits such as 112 are provided for connecting a jack 104 with a jack 105. A keyboard is indicated at 113, 40 and a trunk indicating device is indicated at 116.

A group of connecting units 117, 118, 45 119, etc. is provided for the group of trunks 106, leading to the mechanical exchange 110, and an allotter equipment 121 arranged to select an idle unit of this group may be connected to any keyboard 113 and operates under the control of the corresponding exchange key. One allotter 121 is provided 50 for each group of exchange connecting units having access to the various mechanical offices, and a common group of senders 122 is provided for the use of all operators. The switches 123 and 124 at the mechanical 55 exchange 110 and the circle at 125 are symbolic of the incoming and final switches and a called substation at the mechanical exchange.

The operator at position 100 receives the 60 wanted number from the subscriber at 200 in the usual manner by connecting her telephone set with the subscriber's line through the agency of the cord 112 and jack 104. After having restored her listening key, 65 the operator depresses the key 114 designat-

ing the wanted exchange. In response to the actuation of this key, the allotter 121 operates to seize the preallotted idle connecting circuit 117 and starts the operator's 70 key-set 113 and trunk indicator 116. The operation of the allotter results also in the starting of the trunk selector switch 400 in which the connecting circuit 117 terminates, to hunt for an idle trunk leading 75 to the wanted mechanical exchange. The sender selector switch 401 is operated to associate an idle sender 122 with the selected connecting unit comprising 117 and 400. As soon as the connecting unit is associated with 80 the calling operator's position and the idle sender, a dialing tone is given to the operator who then begins to set up the number wanted on the key board 113. The registering device forming a part of the sender 122 85 is adjusted in accordance with the actuation of the keyboard, and as soon as an idle trunk has been found, the selection of the wanted line at the mechanical exchange is performed under the control of the registering device. At the same time, the number of the selected outgoing trunk is indicated 90 on the trunk indicator 116.

While the selection of the called line is proceeding, the operator inserts the calling 95 plug of the cord circuit 112 into the jack 267 of the outgoing trunk 106, and when the selection is completed the wanted subscriber's bell is rung in the usual manner. The operator's finder switch and associated 100 circuits and the trunk indicator lamps are restored to normal as soon as the operator connects her cord circuit to the outgoing trunk. The operator is thus enabled to set up a new outgoing connection regardless of whether the automatic selecting operations have been completed or not. The trunk selector and associated circuits of the connecting unit are restored to normal as soon as the mechanical selection is completed 110 and revert to common use. The calling line is connected to the called line through cord 112 as soon as the automatic switches have completed their operation. When the subscribers have finished their conversation, the 115 operator severs the connection in the usual manner by removing both plugs from their respective jacks.

120 *Detailed description of operation.*

The detailed operation of the system, will now be described by tracing all the operations performed during the establishment of a connection.

When the subscriber at station 200 removes his receiver from the switchhook the line relay 202 energizes and lights the lamp 203 by means of a circuit through its armature and front contact. On receiving this signal, the operator inserts plug 295 into 125

jack 296 closing a circuit for cut-off relay 297 to extinguish the lamp 203. The operator then manipulates listening key 209 to connect her telephone set 211 to the subscriber's line in the usual manner.

5 The operator, after receiving the wanted number from the subscriber at 200, depresses the office key 114 bearing the name of the office 110. The key 114 completes a circuit from grounded battery, through winding of relay 207, left-hand armature and back contact of relay 210, winding of relay 205, key 114 to ground. Relays 205 and 207 become energized and lock up 10 through the left-hand inner front contact and armature of relay 205, resistance 230, and the left-hand armature and back contact of relay 206. The relay 207 prepares a circuit for the trunk indicating lamps 216, the purpose of which will be herein- 15 after described. The relay 205 closes a circuit at its outer right-hand front contact and armature for the office lamps 208 that indicate to the operator the office for which the call is intended.

25 A further circuit established by the operation of relay 205 unbalances the Wheatstone bridge of allotter 121 to operate the sensitive bridge relay 301. This circuit may be traced from grounded battery, through 30 resistance 330 and relay 301 in multiple with resistance 398, thence through resistance 331, conductor 238, armature and contact of relay 205, to ground.

35 The operation of relay 301 establishes a circuit for operating relays 305 and 405. This may be traced from grounded battery, through the left hand winding of relay 305, conductor 374, left hand winding of relay 405, allotter switch arm 396 and its associated contact, armature and contact of relay 301, to ground. A locking circuit is provided for relay 305 which may be traced from grounded battery through the locking winding and right hand armature and contacts of relay 305, conductor 357, right hand normal armature and contact of relay 406, to ground. Relay 305 establishes a circuit for relay 306 which may be traced 40 from grounded battery, through the winding of relay 306, inner left hand armature and contact of relay 316, right hand armature and contact of relay 305, conductor 357, right hand armature and contact of relay 406, to ground. The operation of relay 306 establishes a circuit for balancing the Wheatstone bridge circuit of allotter 121 which may be traced from grounded battery, through resistance coils 330 and 332, inner 45 right hand armature and contact of relay 306, to ground. The current flow through the Wheatstone bridge resistances 398, 381, 330 and 332 is now equalized and thus the potential in the winding of relay 301 is neutralized to cause its deenergization.

50 Relay 405 in energizing, establishes a locking circuit for itself and an operating circuit for relay 415. The locking circuit for relay 405 may be traced from grounded battery, through the right hand winding of relay 405, right hand inner armature and contact of relay 405, left hand armature and contact of relay 406, to ground. The operating path for relay 415 may be traced from 55 grounded battery, through its winding to the same ground.

55 Relay 415, in attracting its left hand armature, establishes an obvious circuit for operating allotter switch magnet 337. This switch is controlled through its self-interrupting contacts to rotate switch arms 396 and 397 to the terminals of other connecting units.

60 It should be noted that the ground connected to the allotter switch terminal by relay 415 characterizes this connecting unit as busy to prevent the allotter from again selecting this connecting unit until its apparatus has been restored to normal.

65 The progression of switch arms 396 and 397 may bring them into contact with other busy connecting units and thus the switch magnet is repeatedly energized to rotate arms 396 and 397 until an idle connecting unit is encountered. The allotter switch will remain connected to the idle connecting unit but will not actuate the apparatus of 70 said connecting unit until the bridge circuit is again unbalanced by the actuation of another office key similar to 114. The preselection of an idle connecting unit by the allotter saves the time for hunting when an office key is actuated. The allotter 121 is now prepared to be again unbalanced by an operator desiring the use of a connecting unit in this same office group.

75 Conductors 366 and 367 extend to relays similar to relay 205 located in different operators' positions. With grounds connected to conductors 399 and 238, another ground may be connected to conductor 366 to again unbalance the bridge circuit and operate relay 301. This operates the relays in a second connecting unit in the manner of this disclosure and thus a ground is connected 80 to conductor 365 which will again balance the bridge to neutralize the potential through the winding of relay 301. When the relay in the second connecting unit, similar to relay 415, has been operated, switch magnet 337 is energized to rotate the switch arms to select another idle connecting unit. The same process of unbalancing and balancing the Wheatstone bridge takes place 85 as other operators require the services of these circuits.

90 Operators may connect ground simultaneously to conductors 238 and 366 causing the bridge circuit to be unbalanced and relay 301 to operate. A connecting unit is thus 95 130

associated with an operator's position and the allotter switch is propelled by switch magnet 337 in the manner previously described to select another connecting unit. 5 However, in this instance, the ground connected to conductor 399 by the first connecting unit does not balance the bridge and relay 301 remains operated. Upon the selection of a second connecting unit apparatus 10 in that unit is operated to connect a ground to conductor 365, thus balancing the bridge to release relay 301. It will be seen that when the two connecting units have been assigned to the two operators, a ground is 15 connected to conductors 238 and 366 on one side of the bridge and conductors 391 and 365 on the other side of the bridge. In this manner the bridge is balanced to prepare for a third, fourth, etc. connection from operators' positions to associated connecting units. 20

Proceeding with the description of the connecting unit, relay 306 establishes a circuit for the operating magnet 308 of the 25 operator's finder switch 300 as follows: grounded battery, winding, armature and back contact of magnet 308, outer left-hand armature and front contact of relay 306, back contact and armature of relay 310, 30 brush 325, of switch 300, inner left-hand armature and back contact to ground at the relays 205 provided at other operator's position. The magnet 308 is thereby through 35 its self-interrupting armature and back contact, caused to step the operator's finder switch 300 forward until it finds the desired operator's position at which the relay 205 is energized.

During the operation of the operator's 40 finder switch, a circuit is completed for relay 310 in a branch of the driving circuit of magnet 308, this circuit extending through the winding of relay 310 and the inner left-hand armature and front contact 45 of relay 306, to ground. This relay is, however, shunted by direct ground at the back contacts of relays 205 associated with non-depressed office keys. When the test brush 325 engages a terminal at which the office 50 key has been depressed, ground through resistance 230 will be found on this contact. The presence of resistance 230 prevents further operation of magnet 308 and is so designed as to allow relay 310 to operate. 55 The resistance of relay 310 is also great enough to prevent further operation of magnet 308.

Relay 310 closes a circuit from grounded 60 battery, through the winding of relay 207, left-hand armature and back contact of relay 210, the winding, inner left-hand front contact and armature of relay 205, brush 325, armature and front contact of relay 310, and the winding of relay 313 to ground. 65 Relay 313 locks up through a branch cir-

cuit from brush 325, left-hand front contact and armature of relay 305, left-hand armature and front contact and winding of relay 313 to ground.

The operator's keys and trunk indicator 70 equipment are now connected to the connecting unit 117, relays 305 and 405 being operated.

Upon its energization, the relay 405 establishes a circuit for operating magnet 75 408 of the sender selector 401 as follows: grounded battery, winding, armature and back contact of magnet 408, left-hand contact and armature of relay 405, left-hand back contact and armature of relay 410, 80 brush 425, and terminals and leads of busy senders left-hand front contact and armature of relay 701 to ground at the right hand intermediate normal contact and armature of relay 922, or a ground through winding 85 of relay 413. This causes the sender selector magnet 408 to step the switch 401 forward until an idle sender is found, at which time the sender selector magnet 408 is prevented from continuing its operation by the presence 90 of grounded battery at the outer right-hand armature and back contact of relay 701 through the high resistance winding of relay 702, lead 625 and brush 425. Relay 410 is now energized over a circuit as follows: grounded battery, through winding 95 and contacts of magnet 408, left-hand contact and armature of relay 405, winding of relay 410, outer right-hand armature and front contact of relay 405 to ground. The 100 resistance of the winding of relay 410 is such as to prevent the further operation of the sender selector magnet 408. The brushes of the sender selector switch 401 will therefore come to rest on the terminals representing the first idle sender. The relay 410 causes the operation of relay 413 over a circuit as follows: grounded battery, right-hand armature and back contact of relay 701, high resistance winding of relay 702, 110 lead 625, brush 425, left-hand armature and front contact of relay 410, winding of relay 413 to ground. This ground at relay 413 makes the sender busy until relay 701 operates when the busy ground is received 115 through the left-hand front contact and armature of relay 701 from the normal contact and armature of relay 922.

Relays 313 and 413 being energized, the following circuit is established for relay 120 315: grounded battery, relay 315, lead 356, right-hand armature and front contact of relay 410, lead 351, inner right-hand front contact and armature of relay 313 to ground. The relay 315 closes a circuit from 125 grounded battery, through the winding of relay 316, left-hand armature and front contact of relay 315 to ground. Relay 316 becomes energized and closes a locking circuit for itself through its right-hand front con- 130

tact and armature, lead 358, to ground at the left-hand back contact and armature of relay 406. The relay 316 opens the operating circuit for the relay 306 but, inasmuch as this relay 306 is slow to deenergize and relay 316 is quick in action, a circuit will be established for a short interval from dialing tone source 328, through the outer right-hand front contact and armature of relay 306, the outer left-hand front contact and armature of relay 316, conductor 452, brush 329, lead 334, armature and back contact of relay 221, primary winding of induction coil 223 to grounded battery and ground. This dialing tone is transmitted inductively to the operator's telephone set over a circuit as follows: ground, the induction coil of the operator's telephone set 211, outer left-hand armature and front contact of exchange relay 205, secondary winding of induction coil 223 to grounded battery. This dialing tone indicates to the operator that an idle sender has been connected to the keys 113 and that registration of the wanted line number may begin regardless of whether or not the trunk selector has found an idle trunk.

The operation of the trunk selector is accomplished under the control of a relay 415 which operates as soon as relay 405 is operated over a circuit as follows: grounded battery, relay 415, inner right-hand front contact and armature of relay 405, back contact and left-hand armature of relay 406 to ground. The relay 415 closes a circuit for the trunk selector operating magnet 416 from grounded battery, through the winding, armature and back contact of magnet 416, right-hand front contact and armature of relay 415, left-hand back contact and armature of relay 417, brush 428, lead 454 to ground at the relay 502 of busy outgoing trunks or to ground at the left-hand front contact and armature of relay 417 of a busy trunk selector. This circuit causes the operation of the operating magnet 416 which thereupon causes the stepping of the brushes of the trunk selector 400 until an idle trunk is found, at which time the operation of magnet 416 is discontinued. The relay 417 is now operated through a circuit as follows: grounded battery, winding, armature and back contact of magnet 416, inner right-hand armature and front contact of relay 415, relay 417, outer right-hand front contact and armature of relay 415, to ground. During the operation of the magnet 416, relay 417 was short-circuited by the ground at relays like 502. The resistance of relay 417 is such as to prevent sufficient current from flowing through the magnet 416 to operate the magnet and thus the switch is stopped with its brushes resting on the terminals of the first idle trunk encountered and relay 417 connects a ground to brush

428 through its left-hand front contact and armature to establish a busy condition for this trunk.

The relay 417 also establishes an energizing circuit for relays 320 and 422. The circuit for relay 320 is as follows: grounded battery, winding of relay 320, middle right hand armature and front contact of relay 313, lead 355, inner right-hand front contact and armature of relay 417 to ground. The circuit for relay 422 is from grounded battery, through winding of relay 422, inner left-hand armature and front contact of relay 413, leads 359 and 355, to ground at relay 417. The relay 422 connects the leads 447 and 448 of the chosen outgoing trunk through brushes 430 and 431 of the trunk selector 400, armatures and front contacts of relay 422, brushes 432 and 433 of the sender selector 401 to the fundamental circuit leads 620 and 621 of the sender 122. The relay 320 connects the operating leads 342 and 345 for the trunk indicator through brushes 341 and 344, leads 340 and 343 leading to the indicator 116. The leads 342 and 345 are connected through leads 441 and 445 to the trunk indicator operating mechanism at 510. The relay 320 closes a circuit for relay 420 from battery through the winding of relay 420, lead 352, right-hand armature and front contact of relay 320 to ground. Relay 420 establishes a locking circuit for itself through its left-hand front contact and armature, the left-hand back contact and armature of relay 406 to ground. The relay 420 also establishes a circuit for relay 505 from grounded battery, through relay 406, right-hand armature and front contact of relay 420, brush 447, lead 453, the low and high resistance windings of relay 505 to ground. Due to the high resistance of relay 505, relay 406 is not operated at this time but relay 505 is operated. The relay 505 extends through its left hand armatures and front contacts, the fundamental circuit leads 447 and 448 to the outgoing trunk leads 507 and 508. The actuation of the indicator 116 in accordance with the number of the chosen trunk, which it is assumed is 767, will now be described.

It will be remembered that the connection through to the trunk indicator is completed as soon as the trunk selector 400 finds an idle trunk, and before the relay 420 is operated. Since the idle trunk selected is 767, the lead 521 is connected directly to ground, and lead 522 is connected to ground through a resistance. If the hundreds digit of the trunk number had been some other number, a different combination of electrical potentials would have been connected to the leads 521 and 522. Due to the ground on lead 521 a circuit is closed from grounded battery, through the winding of relay 601, winding of relay 602, lead 252, outer left-hand back

contact and armature of relay 226, lead 340, brush 341, inner left-hand front contact and armature of relay 320, lead 342, brush 440, lead 441, lead 521 to ground. Relays 601 and 602 are both energized in this circuit.

5 Relay 601 is marginal and would not have been pulled up if the ground applied at the contacts of relay 509 had included a resistance. Relay 602 is sensitive however and will respond whenever a circuit is closed

10 through it regardless of whether a resistance is included at contacts of relay 509 or not. At the same time a circuit is established from grounded battery through the winding of relay 603, winding of relay 604, lead 251, inner left-hand back contact and armature of relay 226, lead 343, brush 344, outer left-hand front contact and armature of relay 320, lead 345, brush 443, lead 445, the inner

15 upper armature and back contact of relay 509 and lead 522 to ground through the resistance included in lead 522. Relay 604 is a sensitive relay and is energized in this circuit, but since relay 603 is marginal it does not energize. The relays 601, 602 and 604

20 prepare a circuit for the hundreds digit lamp, but this lamp will not be lighted at this time but awaits the operation of certain relays to take place after the tens and units lamps have been selected, as will be hereinafter described. These hundreds digit relays establish locking circuits for themselves from grounded battery, through their respective locking windings to the ground at

25 the relay 207.

30 As soon as the hundreds digit relays are locked up a circuit is established for the relays 227 and 226 as follows: grounded battery, windings of relays 227 and 226 in parallel, lead 260, inner left-hand armature and front contact of relay 602 or outer right-hand armature and front contact of relay 604, lead 259, right-hand make before-break contacts of relay 226, to brush 511 and ground at commutator segment 512. Brush

35 511 and segment 512 are the first active elements in the rotary impulser switch 510 in regards to establishing an indication for the tens and units digits. The relay 226 causes the leads 340 and 343 to be switched over to leads 254 and 253, respectively. By this time relay 505 has operated and a circuit is established through the same brush 511 and commutator contact 512 that caused

40 the operation of relays 227 and 226 for the operation of relay 509 as follows: from grounded battery, through winding of relay 509, outer right-hand armature and front contact of relay 505, continuity contact of relay 509, through the brush 511 and commutator segment 512 to ground. This

45 circuit energized relay 509 and a locking circuit is established for relay 509 from grounded battery, through winding of relay 509, outer armature and front contact

of relay 505, lower front contact and armature of relay 509, to ground. The relay 509 extends the leads 441 and 445 through to brushes 513 and 514, respectively, of the rotary impulser switch 510. A connection is now completed from the rotary impulser switch 510 to the trunk indicator so that the indication of the tens and units digits of the chosen trunk may be effected at the trunk indicator by the continuous rotation of the rotary switch 510, a certain sequence of impulses being sent from the commutator segments of the drum of the rotary switch 510 through these leads to the relays 231 and 229, respectively.

70 The rotary impulser switch 510 is preferably of cylindrical form, but to make the disclosure more readily understood, the cylinder has been developed into a plane rectangular surface. The rotary switch may be constantly driven from any suitable source.

75 It should be noted that regardless of the position of the rotary impulser switch 510 at the time relay 505 is energized no pulses will be sent to the indicator relays until segment 512 is engaged by brush 511. A circuit is thus established to energize relay 509 and the contacts of relay 509 establish 80 energizing paths for the indicator relays as the impulser brushes engage the segments.

85 One of the first segments of the rotary switch 510 that will be associated with the brush 513 is connected to ground. This 90 will complete a circuit for relay 231 from grounded battery through the winding of relay 231, lead 254, and outer left-hand armature and front contact of relay 226 through the switches 300 and 400 to brush 513 and segment 531 to ground. Relay 231 is energized in this circuit. At the same time that brush 513 engages segment 531, brush 514 is brought into engagement with segment 535. A circuit is then completed 95 for relay 229, extending from grounded battery, winding of relay 229, inner left-hand armature and front contact of relay 226, conductor 343, brush 344, outer left-hand armature and front contact of relay 320, brush 443, inner upper armature and front contact of relay 509, conductor 524, brush 514, segment 535 to ground. Relay 229 is energized in this circuit and switches 100 through the impulse leads to the units lamp controlling relays. At the same time that relays 229 and 231 are energized, brush 526 engages segment 537 to energize relay 607 of the tens group and relay 611 of the units group. The circuit of relay 607 extends 105 from grounded battery, left-hand winding of relay 607, conductor 245, outer left-hand armature and front contact of relay 231, conductor 232, brush 526, segment 537 to ground. The circuit of relay 611 extends 110

115 from grounded battery, left-hand winding of relay 607, conductor 245, outer left-hand armature and front contact of relay 231, conductor 232, brush 526, segment 537 to ground. The circuit of relay 611 extends 120

125

130

from grounded battery, left-hand winding of relay 611, conductor 250, outer left-hand armature and front contact of relay 229, conductor 232 to ground, as described. Relays 607 and 611, upon energization, lock up to conductor 236 which is grounded at the left-hand armature and front contact of relay 207.

The impulse switch 510 continues to rotate and when the next row of contacts is brought into engagement with the brush set, brushes 513 and 514 engage contacts 532 and 536. Relays 229 and 231 are again energized. At the same time brush 527 engages segment 538 to energize relay 609 in the tens group and relay 613 in the units group. The circuit of relay 609 extends through the inner left-hand armature and front contact of relay 231 to ground through brush 527 over conductor 233. The circuit of relay 613 extends over conductor 247 and the inner left-hand armature and front contact of relay 229 to ground over the same path. Relays 609 and 613, upon energization, lock up to grounded conductor 236. The next horizontal row of contacts is brought into operative relation with the brush set. Brushes 513 and 514 do not engage contacts. Therefore relays 229 and 231 are deenergized at the time that brush 528 engages segment 539 and no impulses are sent to the controlling relays of either the tens group or the units group.

When the next row of contacts is brought into engagement with the brush set, brush 513 engages segment 533 to energize relay 231, as previously described. Since brush 514 does not engage a segment, relay 229 is not energized at this time. Therefore, when brush 529 engages segment 540, an impulse will be sent to the tens controlling relays only. This impulse pulls up relay 608 over a circuit extending from grounded battery, left-hand winding of relay 608, conductor 242, outer right-hand armature and front contact of relay 231, conductor 235, brush 529 and segment 540 to ground. Relay 608 is energized and locked up to grounded conductor 236.

50 The impulser 510 continues its rotation and when brush 530 engages segment 541, a circuit is completed from grounded battery, left-hand winding of relay 206, armature and front contact of relay 227, brush 530, segment 541 to ground. Relay 206 is energized, and locks up through its right-hand winding and inner right-hand armature and front contact to grounded conductor 236. At the same time, a circuit is completed from grounded battery, winding of relay 228, inner right hand armature and front contact of relay 206 to ground to energize relay 228. Relays 206 and 228, at their various armatures, control the application of ground and battery to the leads

which control the lighting of the number indicating lamps.

The circuit for the No. 7 lamp in the hundreds group extends from grounded battery through lamp 7, outer left-hand armature and back contact of relay 603, outer right hand armature and front contact of relay 601, outer left-hand armature and front contact of relay 604, outer left-hand armature and front contact of relay 602, conductor 258, to ground at the right-hand armature and front contact of relay 228. The circuit for the No. 6 lamp in the tens group extends from grounded battery, outer right-hand armature and front contact of relay 206, conductor 240, outer left-hand armature and front contact of relay 608, lamp 6, inner left-hand armature and front contact of relay 607, left-hand armature and front contact of relay 609, inner right-hand armature and front contact of relay 608 to grounded conductor 236. The circuit for the No. 7 lamp in the units group extends from grounded battery, middle left-hand armature of relay 228, conductor 256, outer left-hand armature and back contact of relay 612, left hand armature and front contact of relay 613, left-hand armature and front contact of relay 611, lamp 7, inner right-hand armature and back contact of relay 612 to grounded conductor 236. As a result of these circuits, the lamps are lighted to indicate that the number of the idle outgoing trunk selected is 767.

The following tabulations give in graphic form the various relay combinations obtainable with the indicating device shown in Fig. 7 for indicating the various digits of a trunk designation.

	Hundreds	105
0—Connect conductor 521 to 441—conductor 522 open. Relays 601 and 602 operated.		
1—Connect conductor 523 to 445—conductor 522 open. Relays 603, 604 and 605 operated.		
2—Connect conductor 521 to 441 and 445. Relays 601, 602, 603, 604 and 605 operated.	110	
3—Connect conductor 522 to 441—conductor 521 open. Relay 602 operated.		
4—Connect conductor 522 to 445—conductor 521 open. Relay 604 operated.		
5—Connect conductor 522 to 441 and 445. Relays 602 and 604 operated.	115	
6—Connect conductor 522 to 441, connect conductor 521 to 445. Relays 602, 603, 604 and 605 operated.		
7—Connect conductor 521 to 441, connect conductor 522 to 445. Relays 601, 602 and 604 operated.	120	
8—Not used.		
9—Not used.		
	Tens	125
0—Connect conductor 523 to brush 0. Relay 608 operated.		
1—Conductor 523 open (not connected). All relays normal.		
2—Connect conductor 523 to brush 2. Relays 607 and 608 operated.	130	

- 3—Connect conductor 523 to brush 3.
Relay 607 operated.
- 4—Connect conductor 523 to brush 4.
Relays 608 and 609 operated.
- 5—Connected conductor 523 to brush 5.
Relay 609 operated.
- 5 6—Connect conductor 523 to brush 6.
Relays 607, 608 and 609 operated.
- 7—Connect conductor 523 to brush 7.
Relays 607 and 609 operated.
- 10 8—Connect conductor 523 to brush 8.
Relays 608 and 610 operated.
- 9—Connect conductor 523 to brush 9.
Relay 610 operated.

Units

- 15 0—Connect conductor 524 to brush 0.
Relay 612 operated.
- 1—Conductor 524 open (not connected).
All relays normal.
- 2—Connect conductor 524 to brush 2.
Relays 611 and 612 operated.
- 20 3—Connect conductor 524 to brush 3.
Relay 611 operated.
- 4—Connect conductor 523 to brush 4.
Relays 612 and 613 operated.
- 5—Connect conductor 524 to brush 5.
Relay 613 operated.
- 25 6—Connect conductor 524 to brush 6.
Relays 611, 612 and 613 operated.
- 7—Connect conductor 524 to brush 7.
Relays 611 and 613 operated.
- 8—Connect conductor 524 to brush 8.
Relays 612 and 614 operated.
- 30 9—Connect conductor 524 to brush 9.
Relay 614 operated.

To vary the hundreds number, a cross connection must be assumed between conductor 521 and either of the upper normal contacts of relay 509, also between conductor 522 and either of the same upper normal contacts. The interchanging of conductors 521 and 522 coupled with the omitting of one or both of these conductors makes possible the combinations given in the tabulation.

To vary the trunk number indications for tens and units, a cross connection must be assumed between conductors 523 and 524 to any one of brushes 0, 2, 3, 4, 5, 6, 7, 8 and 9 as shown in the tabulations. As outlined in the descriptive matter of this specification, relays 509, 226 and 227 are operated when the relays for the hundreds digit have been operated and locked. These relays function as a transfer of control so that a minimum number of conductors can be used extending to the number indicating apparatus, thus transferring conductors 441 and 445 to conductors 523 and 524 under the control of the pulsing mechanism to operate relays 231 and 229 in synchronism with the pulses impressed on conductors 526, 527, 528 and 529 by commutator segments 537, 538, 539, and 540 of the pulsing mechanism.

Since the impression of ground potential on the conductors for operating relays 229 and 231 is synchronized with the impression of ground potential on a conductor for op-

erating relays of the tens and units indicating device, the connection of conductors 523 or 524 to a brush contacting with any segment in a horizontal plane with segment 537 will operate relays 607 or 611. Also the connection of conductors 523 or 524 to a brush contacting with any segment in a horizontal plane with 538 will operate relays 609 or 613.

It is thought that from the foregoing description, the manner in which any desired number may be set upon the indicator will be readily understood by one skilled in the art.

The operator locates the corresponding outgoing trunk jack 267 corresponding to trunk No. 767 and inserts therein the calling plug 265 of the cord circuit 112. This lights the supervisory lamp 266 over a circuit established as follows: Grounded battery, lamp 266, sleeve contacts of plug 265 and jack 267, winding of relay 520, to ground. The relay 520 establishes a circuit for relay 502 as follows: grounded battery, winding of relay 502, inner right-hand front contact and armature of relay 505, front contact and armature of relay 520 to ground. Relay 502 energizes and establishes a locking circuit for itself through its inner right-hand front contact and armature to ground at the front contact and armature of relay 520. The operation of relay 520 causes the trunk indicator to be restored to normal.

The restoration begins with the energization of relay 406 over a circuit as follows: 100 grounded battery winding of relay 406, right-hand armature and front contact of relay 420, brush 447, lead 453, the low resistance winding of relay 505, front contact and armature of relay 520 to ground. The 105 energization of relay 406 breaks the locking circuit for relay 305 and as relay 305 deenergizes, the holding circuit for relays 207, 205 and 313 is broken. These relays are all 110 deenergized due to the fact that the relay 206 is still energized and the original locking circuit for these relays has been broken at the left-hand armature and back contact of relay 206. The deenergization of relay 205 breaks the energizing circuit for the exchange lamps 208, and the original energizing circuit for relay 301. The deenergization of relay 207 breaks the locking circuit for the various relays of the trunk indicator and all of these relays are released. The deenergization of relay 313 breaks the circuit of relay 320.

The deenergization of relays 205 and 313 opens both of the balancing circuits for the allotter 121. It should be noted that relay 313 is slow to deenergize in comparison with relay 205 so as to prevent the energization of relay 301 a second time by the ground at relay 205 and the consequent starting of a connecting unit.

The operator may now prepare a different sender and outgoing trunk provided all the digits of the wanted number have been registered but regardless of whether or not the 5 registers have completed their selection at the mechanical office. It should be remembered that the operator starts to set up the wanted number on the key set 113 as soon as she receives the dialing tone, which takes 10 place before or simultaneously with the operation of the trunk selector 400 and the displaying of the selected trunk on the indicator 116.

Operation of the keys

15 Before describing the registering of the number and the subsequent selection of the wanted number at the mechanical office, it should be understood that the various series of impulses that are to be sent from this exchange for the selection of the proper number at the automatic exchange are not in accordance with the decimal system but that a certain translation scheme is employed 20 which is similar to that shown in the mentioned application by A. E. Lundell, Serial No. 139,511, filed December 29, 1916, and a patent to A. E. Lundell and F. A. Stearn, No. 1,345,016, issued June 29, 1920. In the 25 system described in these applications a mechanical exchange has a capacity of ten thousand subscribers' lines. The subscribers' lines are divided into five groups of two thousand each and each group of two thousand 30 is divided into four groups of five hundred each; each five hundred group is divided into five groups of one hundred each. The impulses representing the thousands and 35 hundreds digits bring about various selections which will extend the incoming trunk leads to a group of one hundred lines in which the tens and units selections will be 40 made in accordance with the decimal system.

The series of impulses controlled by the 45 thousands and hundreds keys in the wanted number 4789 used in this description, are as follows: For the thousands digit No. 4, three impulses are sent which determine in which group of two thousand a selection 50 shall be made. The thousands and hundreds digits jointly control the sending of two impulses to control the selection of the proper group of 500 lines. The hundreds digit No. 7 will then control the sending of 55 three impulses to determine in which of five groups of one hundred each selection is to be made. In a ten thousand line exchange, the thousands impulses are from 1 to 5 to 60 select a group of two thousand out of a total of five groups, the hundreds impulses are from 1 to 4 to select a group of five hundred out of a total of four groups in a two thousand group, followed by from 1 to 5 impulses to select a group of one hundred out 65

of a total of five groups in a five hundred group.

The setting up of the digits of the wanted number on the operator's key set 113 will now be described. It will be remembered that at the time the connecting unit 117 has found an idle sender, a dialing tone was transmitted to the operator indicating that the setting up of the number of the wanted subscriber may take place. It should also be noted that this setting up of the number may begin before the connecting unit 117 has found an idle outgoing trunk, that is, the setting up of the number may take place simultaneously with the operations necessary to find an outgoing trunk. 70 75 80

It has been assumed that the subscriber's line having the number 4789 was to be selected. As soon as an idle sender was associated with the connecting unit a control 85 circuit was completed from the operator's keyboard 113 to the register and control equipment. This controlling circuit comprises three leads that are connected to the thousands register relays, 802, 803, 804 and 805. A path extends from grounded battery, through a winding of relay 802, lead 720, outer right-hand back contact and armature of relay 712, winding of relay 715, lead 622, brush 490, lead 450, inner right-hand armature and contact of relay 315, conductor 450, brush 353, lead 346, to keys 113. A second path may be traced from grounded battery, windings of relays 804 and 803 in series, lead 721, middle right-hand back contact and armature of relay 712, lead 623, brush 455, lead 451, middle right-hand armature and contact of relay 315, lead 451, brush 354, lead 347 to keys 113. A third path leads from grounded battery, through a winding of relay 805, lead 722, inner back contact and armature of relay 712, inner right-hand back contact and armature of relay 701, lead 624, brush 456, lead 452, outer right-hand armature and contact of relay 315, lead 452, brush 329, lead 334, right-hand armature and back contact of relay 221, induction coil 223, to grounded battery. 100 105 110 115

Upon the depression of key No. 4 for the 115 thousands digit, a circuit is established from grounded battery, through the left hand winding of relay 802, the left-hand front contact of key No. 4 and resistance 260, to ground. Another circuit is established for relays 804 and 803 from grounded battery, through the left hand windings of relays 804 and 803, and the right-hand contact of key No. 4, to ground. Due to the fact that the resistance 260 is in the circuit for the marginal relay 802, it does not operate but there is sufficient current passing through this circuit to operate relay 715. The relay 715 establishes a circuit for counting relay 705 120 125 130 as follows: grounded battery winding of re-

lay 705, inner left-hand back contact and armature of relay 704, front contact and armature of relay 715, to ground. The relays 804 and 803 become energized and establish locking circuits for themselves from grounded battery through their right-hand front contacts and armatures, normal contact and armature of relay 701, to ground, at relay 922. As soon as the thousands key 5 is released, the relay 715 becomes deenergized and removes the shunt path from the winding of relay 704, whereupon relay 704 becomes energized and relay 705 locked up by current flowing from grounded battery, through windings of relays 705 and 704, right-hand front contact and armature of relay 705, left hand normal contact and armature of relay 701, to ground, at the right-hand intermediate normal contact and armature of relay 922. The relay 704 establishes 10 through its right-hand inner armature and front contact an energizing circuit for relay 712. The relay 712 causes the extension of the three controlling leads 622, 623 and 624 from leads 720, 721 and 722 to leads 15 723, 724 and 725, respectively.

The depression of the hundreds digit key 20 No. 7 causes a circuit to be established from grounded battery, through the left hand winding of relay 806, the left-hand contact of key No. 7, and the low resistance winding of relay 221, to ground. This energizes relays 806 and 221, and due to the energization of relay 221 a circuit is established from 25 grounded battery, through the winding of relay 809, the armature and front contact of relay 221 to ground. This circuit energizes relay 809, and relays 806 and 809 are locked up over a circuit from grounded battery, through their respective locking windings, left hand normal contact and armature of relay 701, to ground at relay 922. The relay 715 is again energized but is now in series with relay 806. The relay 715 completes 30 a circuit for relay 707 as follows: grounded battery, winding of relay 707, left-hand back contact and armature of relay 706, inner left-hand front contact and armature of relay 704, front contact and armature of relay 715, to ground, to energize relay 707.

As soon as the hundreds digit key is released, the relay 715 becomes deenergized and permits the energization of relay 706, 35 the circuit being closed from grounded battery, through the windings of relays 707 and 706 in series, front contact and armature of relay 707, left-hand normal contact and armature of relay 701, to ground, at relay 922. The relay 706 establishes a circuit for relay 713 from grounded battery, through relay 713, right-hand front contact and armature of relay 706 to ground. The relay 713 causes the extension of the three controlling leads 622, 623 and 624 from leads 40

723, 724 and 725 to 727, 728 and 729, respectively.

Upon the depression of the tens digit key 45 No. 8, a circuit is established for relay 810 from grounded battery, through the winding of relay 810, the left-hand contact of key No. 8, low resistance winding of relay 221, to ground. Another circuit is extended from grounded battery through the left hand windings of relays 812 and 811 in series, the right-hand contact of key No. 8 and low resistance winding of relay 221, to ground. Relay 221 is operated and a circuit is established for relay 813 from grounded battery through the left hand winding of relay 813, right-hand armature and front contact of relay 221, to ground. The relays 810, 811, 50 812 and 813 are operated and establish locking circuits for themselves from grounded battery, through their locking windings, right-hand front contacts and armatures, left-hand normal contact and armature of relay 701, to ground at relay 922. Relay 715 is now energized in series with relay 810 and closes a circuit from grounded battery, 55 through the winding of relay 709, left-hand back contact and armature of relay 708, left-hand front contacts and armatures of relays 706 and 704 in series, through front contact and armature of relay 715, to ground. When 60 the tens digit key is released, relay 715 de-energizes and relay 708 is energized and locked up in series with relay 709 from grounded battery, through the windings of relays 709 and 708, front contact and armature of relay 709, left-hand normal contact and armature of relay 701, to ground at 65 relay 922.

The relay 708 establishes a circuit for relay 714 as follows: grounded battery, winding of relay 714, right-hand front contact and armature of relay 708, to ground. This energizes relay 714 whose armatures switch the controlling leads from leads 727, 728 and 729 to leads 731, 732 and 733 and the circuits 70 are now ready to receive the units impulses.

In response to the depression of the units digit key No. 9, the following circuits are established: grounded battery, left hand winding of relay 814, relay 715, through to left-hand contact of key No. 9, high resistance winding of relay 221, to ground. Due to the high resistance in this circuit, the relay 814, which is marginal, does not energize but relay 221 does energize. A second circuit is established from grounded battery, through the left hand windings of relays 816 and 815 in series, through to the right-hand contact of key No. 9, the low resistance winding of relay 221, to ground. The relay 221 establishes a circuit for relay 818 as follows: grounded battery, left-hand winding of relay 818 through to right-hand armature and front contact of relay 221, to ground. Relays 815, 816 and 818 are energized and 75 80 85 90 95 100 105 110 115 120 125 130

locked up over their respective locking windings through normal contacts of relay 701, to ground at relay 922. Upon the energization of relay 715 a circuit is established for relay 711 as follows: grounded battery, winding of relay 711, left hand back contact and armature of relay 710, left-hand armatures and front contacts of relays 708, 706 and 704 in series, to front contact and armature of relay 715, to ground. Upon the de-energization of relay 715 in response to the release of the units digit key No. 9, relay 710 is energized and relays 711 and 710 are locked up over a circuit from grounded battery, through windings of relays 711 and 710 in series, front contact and armature of relay 711, left-hand normal contact and armature of relay 701, to ground at relay 922.

All the register relays necessary for the control of the impulses representing the number 4789 are now locked up and the selection at the mechanical office may take place.

The selection at the mechanical office will begin as soon as the outgoing trunk has been found and the thousands key is released, as the fundamental circuit from trunk leads 507 and 508 is then extended through to the counting relays as follows: From lead 507, through outer left-hand armature and front contact of relay 505, lead 447 brush 430, upper armature and front contact of relay 422, brush 433, lead 621, outer left-hand armature and front contact of relay 704, lead 621, left-hand armature and back contact of relay 920, windings of stepping relay 916, left-hand armature and back contact of relay 900, back contact and armature of relay 915, lead 620, brush 432, inner front contact and armature of relay 422, brush 431, lead 448, inner left-hand front contact and armature of relay 505, trunk lead 508. These trunk leads are to be extended to the called station 925 through incoming switch Fig. 8 and final switch Fig. 9. Under the control of the commutator associated with the incoming selector, the stepping relay 916 operates three times. In response to the first energization of relay 916 a circuit is established as follows: from grounded battery, through the inner right-hand armature and back contact of relay 917, back contact and armature of counting relay 0', winding of counting relay 4, back contact and armature of relay 4', back contact and armature of relay 923, front contact and armature of relay 916, to ground. This operates counting relay 4. Counting relay 4' is shunted at the front contact of relay 916. Upon the first deenergization of relay 916 counting relay 4' is permitted to energize and is locked up in series with counting relay 4.

Counting relay 3 energizes as soon as relay 916 is energized a second time, and when

it is deenergized, relays 3 and 3' are locked up.

Upon the third energization of relay 916, a circuit is completed from grounded battery, inner right-hand armature and back contact of relay 917, armature and back contact of the 0' counting relay, through the winding of the 0 counting relay, conductor 950, outer armature and back contact of relay 902, conductor 823, left-hand armature and back contact of relay 805, outer left-hand armature and back contact of relay 801, outer right-hand armature and back contact of relay 802, outer right-hand armature and front contact of relay 803, to conductor 831, thence to conductor 831 in Fig. 5 through the armatures and front contacts of counting relays 3' and 4', thence by way of conductors 941, and 930 to ground at the armature and front contact of relay 916. This circuit operates counting relay 0 and upon the subsequent deenergization of relay 916, counting relay 0' and relay 915 become energized. When relays 0' and 915 operate, the originally traced locking circuit including the back contact and armature of relay 0' is broken, but the counting relays are maintained locked up through the left-hand winding of relay 917, to grounded battery. The relay 917 becomes energized and a circuit is established for relay 900 as follows: grounded battery, winding of relay 900, left-hand front contact and armature of relay 917, front contact and armature of relay 705, to ground. The relay 900 breaks the locking circuit for all the counting relays including relay 915. It will be noted that relay 915 had previously opened the fundamental circuit at its left-hand back contact and armature and that relay 900 maintained the fundamental circuit open while relay 915 deenergized. This breaking of the fundamental circuit causes the incoming selector to trip a brush that has access to the desired group of two thousand lines. The relay 917 establishes a circuit for relay 901 as follows: grounded battery, winding of relay 901, inner back contact and armature of relay 902, outer right-hand front contact and armature of relay 917, to ground. This energizes relay 901. The relay 901 closes a circuit for the relay 917 as follows: grounded battery, right-hand winding of relay 917, inner right-hand armature and back contact of relay 922, outer left-hand armature and front contact of relay 901, conductor 726, right-hand back contact and armature of relay 706, to ground. However, this holding circuit for relay 917 will be effective only if the hundreds digit key has not been depressed in which case the counting relays will wait until the depression of the hundreds digit key takes place. This is to insure that the mechanical selection shall wait for the setting up of the

number. There is a circuit like the above established for relay 917 between each digit by the counting relays 901, 906 and 908 and the right-hand back contacts and armatures of relays 706, 708 and 710 in succession but no further reference will be made to these circuits, as it will be assumed that the setting up of the number and locking up of the relays has taken place before the starting of the mechanical selection.

Relay 917 also establishes a circuit for energizing the very slow operating dash pot relay 919, the utility of which will be described later.

If, as in the present case, the hundred keys have been depressed, the relay 706 is energized, and the above traced circuit including the right-hand winding of relay 917 is not established. The relay 917 becomes thus deenergized upon the energization of slow acting relay 900 and opens the circuit of the latter. When relay 917 deenergizes, the shunt is removed from the winding of relay 902, and this relay energizes. The fundamental circuit is now again closed, and the incoming switch at the mechanical office is again started. Under the control of the incoming selector the relay 916 is operated and a circuit is established as follows: grounded battery, inner right-hand armature and back contact of relay 917, back contact and armature of counting relay 0', winding of counting relay 4, back contact and armature of counting relay 4' back contact and armature of relay 923, front contact and armature of relay 916, to ground. Upon the first deenergization of relay 916, the counting relays 4' and 4 are locked up. This extends the circuit through to lead 830', and at the next energization of the relay 916, a circuit is established from grounded battery, through the right-hand armature and back contact of relay 917, back contact and armature of 0' relay, winding of counting relay 0, conductor 950, outer right-hand armature and front contact of relay 902, outer right-hand armature and back contact of relay 905, right hand armature and back contact of relay 801, right-hand outer armature and front contact of relay 809, lead 830', the front contact and armature of counting relay 4', back contact and armature of relay 923, front contact and armature of relay 916, to ground. Counting relay 0 is energized in this circuit and upon the subsequent deenergization of relay 916, counting relay 0' and relay 915 are energized as previously described. This causes the energization of relay 917 which in turn energizes relay 900 and the fundamental circuit is again broken as in the previous case. The relay 917 in this case establishes a circuit for relay 903 as follows: grounded battery, winding of relay 903, inner armature and back contact of relay 905, inner right-hand front contact

and armature of relay 902, outer right-hand armature and contact of relay 917, to ground. Relay 900 not only breaks the locking circuit for the counting relays, but also the circuit for relay 917. The deenergization of relay 917 causes the reestablishment of the fundamental circuit and a second series of impulses, due to the depression of the hundreds key will be transmitted. It will be noted that the deenergization of relay 917 causes the operation of relay 905 and the locking up of relays 903 and 905 over a circuit as follows: grounded battery, winding of relay 903, winding of relay 905 in series, front contact and armature of relay 903, left hand normal contact and armature of relay 701, to ground at the relay 922. The third series of groundings of the fundamental circuit at the mechanical office begins after the original closing of the fundamental circuit, when relay 916 operates, and a circuit is established to energize counting relay 4, and due to the continued interruption of the fundamental circuit at the mechanical office, the relay 916 is energized and deenergized in the same manner as before until the counting relays 4 and 4' and 3 and 3' are locked up. The next energization of relay 916 establishes a circuit for the 0 counting relay as follows: grounded battery, inner right-hand armature and back contact of relay 917, contacts of counting relay 0', winding of counting relay 0, outer right hand armatures and front contacts of relays 902 and 905, middle armature and back contact of relay 907, lead 824, left-hand armature and back contact of relay 807, outer right-hand armature and front contact of relay 806, lead 831, front contacts and armatures of relays 3' and 4' in series, back contact and armature of relay 923, front contact and armature of relay 916, to ground. The operation of relays 0' and 915, 917 and 900 takes place in sequence as previously stated, and the locking circuit for the counting relays is broken as before. Upon the energization of relay 917, relay 906 is energized by a circuit from grounded battery, through relay 906, right-hand back contact and armature of relay 907, inner right-hand front contacts and armatures of relays 905 and 902 in series, outer right-hand front contact and armature of relay 917, to ground. Upon the subsequent deenergization of relay 917, relays 906 and 907 are locked up.

It will be noted that at the energization of relay 813, a circuit was partly completed for relay 923 and at the locking up of relay 907, this circuit is completed as follows: grounded battery, winding of relay 923, outer right-hand armature and back contact of relay 909, outer right-hand front contact and armature of relay 907, lead 826, left-hand front contact and armature of

relay 813 to ground. This energizes relay 923 and switches the lead 930 from lead 941 to 942. When, therefore, the fundamental circuit is closed as in previous cases, a circuit is established for counting relay No. 9 at the first energization of relay 916. The fundamental circuit is now shunted by the commutator at the final selector switch in the mechanical office a number of times and for each shunting a set of counting relays is energized and locked up until the sets 9 and 9' to 2 and 2', inclusive, have been energized and locked up. At this time a circuit is established for the 0 counting relay as follows: grounded battery, inner right-hand armature and back contact of relay 917, back contact and armature of the 0' relay, winding of the 0 counting relay, outer right-hand armature and front contact of relays 902 and 905 and middle armature and front contact of relay 907, middle armature and back contact of relay 909, lead 821, left-hand armature and front contact of relay 811, left-hand armature and front contact of relay 810, left-hand armature and front contact of relay 812, lead 832, right-hand armatures and front contacts of counting relays 2' to 9' inclusive, in series, front contact and armature of relay 923, front contact and armature of relay 916, to ground. The subsequent deenergization of stepping relay 916 causes the operation of counting relay 0' and relay 915. The operation of counting relay 0' causes the energization of relay 917, and the energization of relay 917 causes the energization of relay 900, and the locking circuits for the counting relays are thereby broken and the fundamental circuit is opened, as previously described.

40 The relay 917 establishes a circuit for relay 908 as follows: grounded battery, winding of relay 908, inner right-hand back contact and armature of relay 909, inner right-hand front contacts and armatures of relays 907, 905 and 902 in series, outer right-hand front contact and armature of relay 917, to ground. The energization of relay 908 establishes a locking circuit for relay 917 as follows: grounded battery, winding of relay 917, inner right-hand armature and back contact of relay 922, outer left-hand armature and front contact of relay 908, lead 734, right-hand back contact and armature of relay 710, to ground. The operation of relay 710 breaks the locking circuit for relay 917. The deenergization of relay 917 permits relay 909 to be energized and locked up in series with relay 908 as follows: grounded battery, winding of relay 908 and 909 in series, inner left-hand front contact and armature of relay 908, to ground at relay 922. The energization of relay 909 causes the release of relay 923, but the circuit for relay 923 is again established as follows: grounded battery, winding of relay

923, outer right-hand armature and front contact of relay 909, lead 825, left-hand contact, and armature of relay 818, to ground.

5 Due to the reestablishment of the circuit for relay 923, the lead 930 remains in connection with lead 942. Therefore, when the fundamental circuit is again established and on the first energization of relay 916, a circuit is established for counting relay No. 9 and each interruption of the fundamental circuit a set of counting relays is locked up beginning with 9 and 9' and ending with 1 and 1'. When counting relay 1' has been energized a circuit is established as follows: grounded battery, inner right-hand armature and back contact of relay 917, armature and back contact of relay 0', winding of 0 counting relay, the outer left-hand armatures and front contacts of relay 902, 905 and middle armatures and front contacts of relays 907 and 909 in series, lead 820, left-hand armature and front contact of relay 815, left-hand armature and back contact of relay 814, outer right-hand armature and front contact of relay 816, lead 833, right-hand armatures and front contacts of counting relays 1' to 9' inclusive, lead 942, armature and front contact of relay 923, lead 930, front contact and armature of relay 916, to ground. The subsequent deenergization of stepping relay 916 causes the energization of relays 917 and 909 as previously described, and the fundamental circuit is finally broken.

10 All the impulses necessary to advance the switches at the mechanical office have now been sent and there is no further use for the register controlling equipment.

Release of the operator's equipment

105 The release of the operator's equipment and its return to common use will now be described.

110 It will be remembered that as soon as the operator inserted her calling plug in the outgoing trunk jack 267, the trunk indicator was returned to normal. Therefore, as soon as the mechanical selection has been completed, the register controlling equipment will be returned for common use and the connecting unit 117 will also be returned for common use and the connection from the operator's cord circuit will be connected through to the outgoing trunk and through the switches at the mechanical office to the 115 called line. The ringing of the called station will then take place.

120 It is to be noted that upon the final energization of relay 917 a circuit is completed for energizing relay 990 by the way of the back contact of relay 991 and the inner front contacts of relays 909, 907, 905 and 902. As soon as the counting relays are restored due to the operation of relay 909, relay 917 is deenergized and allows relay 130

991 to become energized. Relay 991 upon energization completes a circuit from grounded battery, through the winding of relay 701, conductor 735, outer right hand armature and back contact of relay 922, to ground through the armature and contact of relay 991 operating relay 701. Also a circuit is established from grounded battery through the winding of relay 920, inner left hand armature and front contact of relay 991, to ground, operating relay 920. Relay 701 in attracting its left hand armature opens one holding circuit for the register relays. Another holding circuit, however, is maintained through the contact and armature of relay 918 to ground. Relay 920 in attracting its right hand armature establishes an obvious circuit for energizing relay 918. Since relay 918 is slow-to-operate, this armature will maintain this substitute holding circuit for the register relays for a given time interval. Relay 701 in attracting its right hand armature removes the energizing circuit for relay 413 thus causing its release. Relay 701 in attracting its left hand armature connects ground to lead 625 to maintain the register control equipment busy until the connecting unit has been finally released.

30 The deenergization of relay 413 removes the holding ground for relays 405, 420 and 316. The deenergization of relay 405 causes the deenergization of relay 415 and relay 410 and also breaks the original operating circuit for the sender operating magnet. The deenergization of relay 415 breaks the energizing circuit for relay 417 and the operating circuit for trunk selecting magnet 416. The deenergization of relay 415 also removes the ground from the lead 350 that was connected to an allotter and thus removes the busy condition from the connecting unit. This connecting unit can therefore again be seized by the allotter.

45 The time period for operating relay 918 is of sufficient duration to allow the release of the connecting unit relays. Upon the energization of relay 918 the holding ground for the register relays, relays 704 to 711, inclusive, and relays 901, 902, 903, 905 to 909, 990 and 991 are opened, thus causing their release. The release of relay 991 opens the operating circuit for relays 920 and 701, thus causing their release

55 which will in turn cause the release of relay 918. The busy ground is now removed from the register controlling equipment conductor 625 and since this equipment has been completely restored to normal it is again available for use in conjunction with other connecting units.

It will be noted that the energizing circuit for relay 422 that was maintained through the contacts of relays 417 and 413, was already broken upon the deenergization

of relay 413. Upon the deenergization of relay 420, the energizing circuit for relay 406 is broken. Simultaneously with the breaking of the circuit 320 the energizing circuit for relay 315 was broken at the contact of relay 410.

70 The deenergization of relay 315 breaks the energizing circuit for relay 316 and disconnects the leads 450, 451 and 452 from the brushes 353, 354 and 329 respectively, of the operator's finder.

75 It will be remembered that when a call is initiated by a subscriber, the operator at the manual exchange responds to the line signal in the usual manner and receives the number of the subscriber's station to which the calling party wishes to be connected. The system herein described provides for calls to be completed to a subscriber's station in an automatic telephone office. This is accomplished by the operator actuating an office key 114 to control the selection of a trunk to a given automatically operated office and by actuating a series of keys representing the digits of the number of the subscriber's station to which the call is to be extended. The actuation of the above keys actuates apparatus in various parts of this circuit including the sender register relays to control the incoming selector switch shown in Fig. 8 and the final selector switch shown in Fig. 9.

90 These calls may be abandoned by the operator in various stages of incompleteness as follows:

95 A. A call may be abandoned by the subscriber at a time when the operator has part of the digits registered, but since the call is abandoned, the operator will not complete the registration of the full number of digits. The actuation of the keys in the operator's position operates a connecting link and the register relays of the sender. If the operator has inserted plug 265 in the trunk jack 267, the incoming selector switch and possibly the final selector switch is actuated. Since the selector switches are not sent forward to complete the connection to the called station, one of the selector switches is stopped in the position in which it is resting after responding to the pulses for the digit representing the last key actuated by the operator.

100 B. The operator may have depressed the office key 114 when the calling subscriber abandons the call. Therefore the operator may not actuate the digits keys to register the number. The office key, however, actuates the allotter relay 301 which in turn starts the apparatus of a connecting link to select an idle sender, an idle trunk and the operator's position.

105 A means of releasing apparatus held in an actuated position by partial completion of a service connection is shown in Fig. 5 of

130

80

110

115

120

125

this disclosure. In order that the description of this releasing means be well understood, a detailed description of the selector switches shown in Figs. 8 and 9 will be first made.

5 It will be remembered that relays 505 and 422 are operated and switches 400 and 401 are in a position to associate the selected sender with the trunk conductors 507 and 422 when the incoming and final selecting switches are under the control of the register relays. The fundamental circuit is thus established for actuating relay 870 in the incoming selector Fig. 8. This may be 10 traced from grounded battery through lower right and left hand contacts of sequence switch spring 854, left hand normal contacts of relay 871, winding of relay 870, lower right hand and upper left hand contacts of sequence switch spring 850, tip conductor of trunk, left hand outer armature and contact of relay 505, conductor 447, switch arm 430 and associated contact, upper armature and contact of relay 422, 15 switch arm 433 and associated contact, conductor 621, left hand outer armature and contact of relay 704, left hand normal armature and contact of relay 920, winding of relay 916, left hand normal armature and 20 contact of relay 900, left hand contact and normal armature of relay 915, conductor 620, switch arm 432 and associated contact, upper inside armature and contact of relay 422, switch arm 431 and associated contact, 25 conductor 448, left hand inner armature and contact of relay 505, conductor 508, upper left hand contact of sequence switch spring 868 to ground.

Since the operation of the stepping relay 40 and counting relays has been hereinbefore described in detail, it is not thought necessary to again describe it along with the operating features of the selector switches.

Relay 870 in attracting its outer right 45 hand armature establishes an actuating circuit for sequence switch magnet 840. This may be traced from grounded battery through the winding of sequence switch magnet 840, lower and upper right hand contacts of sequence switch spring 855, contact and armature of relay 870 to ground thus moving the sequence switch from position 1 to position 2.

In position 2 of the sequence switch, a 50 circuit is established for controlling brush selection. Relay 870 remains energized over a holding circuit including the fundamental circuit previously traced. This holding circuit may be traced from grounded battery through the lower right and left hand contacts of sequence switch spring 854, left hand normal contacts of relay 871, winding of relay 870, upper left hand and right hand contacts of sequence switch spring 851, inner right hand contact and

50 armature of relay 870, upper right hand and left hand contacts of sequence switch spring 850 and thence over the tip conductor of the trunk and fundamental returning over the ring conductor of the fundamental and to ground through the upper left hand contacts of sequence switch spring 868.

A circuit is established through the contacts of relay 870 for actuating the up-drive magnet 842. This may be traced from grounded battery through magnet 842, upper right hand and lower left hand contacts of sequence switch spring 862, to ground at the outer armature and contact of relay 870. As the elevator of the selector switch is driven in an upward movement, brush 888 moves to a position of contact with commutator 892 and in its upward movement connects ground intermittently through the metal segments of the commutator establishing intermittently a shunt path for stepping relay 916 to cause it to be intermittently deenergized. This shunt path may be traced from ground through the lower right hand contact of sequence switch spring 866, brush 888, commutator segment 892, upper and lower left hand contacts of sequence switch spring 858 to the armature of relay 870. This shunt circuit while causing the deenergization of the stepping relay 916, however, does not affect the holding circuit of relay 870 which remains energized.

It will be remembered that the stepping relay 916 is held in an operated position over the fundamental circuit in series with relay 870. The intermittent energization and deenergization of the stepping relay 916 operates a series of counting relays shown 105 in Fig. 5. The number of counting relays operated depends upon the setting of the register relays as previously described.

Counting relays 915 and 0' are the last 110 counting relays energized from a series of energizations and deenergizations of stepping relay 916, the fundamental circuit being then opened causes the relay 870 to release when brush 888 reaches an insulated segment of the commutator.

The deenergization of relay 870 opens the energizing path for updrive magnet 842 arresting the upward movement of the selector switch elevator. A circuit is also established for energizing sequence switch magnet 840. This may be traced from grounded battery through magnet winding 840, lower right hand and upper left hand contacts of sequence switch spring 855 to ground through the outer normal contact and armature of relay 870. Thus the sequence switch is moved from position 2 to position 3.

In position 3 of sequence switch 840, relay 870 will again be energized as soon as the fundamental circuit is closed by the de-

energization of the counting relays shown in Fig. 5. Relay 870 in attracting its outer right hand armature establishes a circuit for energizing sequence switch magnet 840. This may be traced from grounded battery through the winding of magnet 840, lower and upper right hand contacts of sequence switch spring 855, to ground through the outer right hand spring and armature of relay 870 thus moving the sequence switch into position 4. The inner right hand contact and armature of relay 870 establishes a holding circuit for this relay effective as the sequence switch moves out of position 3. This holding path is the same as previously traced.

The sequence switch in positions 3 and 4 establishes an obvious circuit for trip magnet 843. The energizing of trip magnet 843 causes the brushes 880, 881 and 882 to be released for engagement with the bank terminals in the manner well known in the art upon a subsequent movement of the switch elevator.

With sequence switch 840 in position 4, a circuit is again established to energize the updrive magnet 842. This circuit may be traced from grounded battery through the winding of the updrive magnet 842, upper right hand and lower left hand contacts of sequence switch spring 862 to ground through the outer right hand contact and armature of relay 870. As the elevator of the selector switch is driven in an upward movement, brush 887 moves to a position of contact with commutator 893 and in its upward movement connects ground intermittently to the metal segments of the commutator establishing intermittently a shunt path around stepping relay 916 to cause it to be intermittently deenergized. This shunt path may be traced from ground through the lower right hand contacts of sequence switch spring 866 brush 887, commutator 893, lower left hand and upper right contacts of sequence switch spring 850, to the armature of relay 870.

The intermittent energization and deenergization of stepping relay 916 causes a series of counting relays to operate thus opening the fundamental circuit when counting relay 915 is energized. Relay 970 is then deenergized and thus opens the energizing circuit for the updrive magnet 842 arresting the upward movement of the selector switch elevator. A circuit is also established for energizing sequence switch magnet 840. This circuit may be traced from grounded battery through the winding of magnet 840, lower right and upper left hand contacts of sequence switch spring 855 to ground through the outer normal spring and armature of relay 870.

The energization of sequence switch magnet 840 causes the movement of the sequence

switch from position 4 to position 5. When the counting relays shown in Fig. 5 are released, the fundamental circuit is again closed to again operate relay 870. The path for the operation of relay 870 is the same as hereinbefore traced. The contacts of relay 870 do not establish any operating circuits until the sequence switch 840 reaches position 7.

In position 5 of sequence switch 840, a circuit is established for the operation of relay 877. This may be traced from grounded battery, through lower and upper right hand contacts of sequence switch spring 859, left hand winding of relay 877, upper left hand and lower right hand contacts of sequence switch spring 866, to ground. Relay 877 in attracting its left hand armature establishes a circuit for moving sequence switch 840 from position 5 to position 6. This may be traced from grounded battery through winding of magnet 840, lower left hand and right hand contacts of sequence switch spring 855 to ground through left hand contact and armature of relay 877.

Since the selector switch is now resting on the first terminal of the selected group of terminals, relay 877 will remain actuated if said first terminal is busy or will release if it is not busy.

Assuming that the first terminal is busy the path for holding relay 877 actuated may be traced from grounded battery, through the right hand winding of relay 877, lower right hand contact of sequence switch spring 860, right hand contact and armature of relay 877, brush 880, terminal 878, to ground on a circuit the same as that shown in Fig. 8. This ground is derived from the upper right hand contacts of a sequence switch spring the same as 867 connected to a brush the same as 880.

With relay 877 in an operated position, a circuit is established for actuating the updrive magnet 842. This may be traced from grounded battery, through the winding of updrive magnet 842, upper and lower right hand contacts of sequence switch spring 856, left hand contact and armature of relay 877, to ground. The sequence switch elevator is thus driven in an upward movement seeking an idle trunk to a final selector such as is shown in Fig. 9. This idle trunk will be characterized by the absence of ground on the sleeve terminal thereof and thus the holding circuit for relay 877 will be opened causing said relay to release.

The release of relay 877 opens the energizing circuit for updrive magnet 842, thus arresting the upward movement of the switch elevator.

The release of relay 877 also establishes an actuating circuit for sequence switch magnet 840, which may be traced from grounded battery through the winding of

magnet 840, lower and upper right hand contacts of sequence switch spring 858, to ground through left hand normal contact and armature of relay 877, thus moving the sequence switch from position 6 to position 7. Since line relay 870 is energized over the fundamental circuit, a circuit is established for moving the sequence switch from position 7 to position 8. This may be traced from grounded battery, through the winding of sequence switch magnet 840, lower and upper right hand contacts of sequence switch spring 855, to ground through outer right hand contact and armature of relay 870.

In position 8 of sequence switch 840, a circuit is established for controlling the final selector shown in Fig. 9 to select the wanted line. A circuit is established for operating relay 933 which may be traced from grounded battery, through both windings of said relay, upper left hand contact of sequence switch spring 964, tip conductor 995, terminal 885, brush 882, lower contacts of sequence switch spring 862, to ground through outer right hand contact and armature of relay 870. Relay 933 in attracting its left hand armature establishes a circuit for operating relay 934. This may be traced from grounded battery, through winding of relay 934, lower left hand and upper right hand contacts of sequence switch spring 961, to ground through left hand contact and armature of relay 933. Relay 934 in attracting its left hand armature, establishes a circuit for actuating sequence switch magnet 960. This may be traced from grounded battery through the winding of sequence switch magnet 960, upper right hand contact of sequence switch spring 965, to ground through the left hand contact and armature of relay 934. The sequence switch 960 is thus moved from position 1 to position 2 where final brush selection takes place. It should be noted that a locking circuit is established for relay 933 which may be traced from grounded battery, through its windings, upper and lower left hand contacts of sequence switch spring 962, right hand contact and armature of relay 933, upper right hand contact of sequence switch spring 964, conductor 995, terminal 885, brush 882, lower contacts of sequence switch spring 862, to ground through the outer front contact and armature of relay 870. A circuit for updrive magnet 939 is thus established from grounded battery through the winding of said magnet, upper right hand and lower left hand contacts of sequence switch spring 962, right hand contact and armature of relay 933, upper right hand contact of sequence switch spring 964, conductor 995, terminal 885, brush 882, lower contacts of sequence switch spring 862, to ground, through the right hand contact and armature of relay 870. The elevator of the final selector switch is driven in an upward move-

ment and brush 944 intermittently connects with the metal segments of commutator 948 to establish a shunt path for intermittently releasing the stepping relay 916 shown in Fig. 5. This shunt circuit may be traced from ground through to the left hand armature and contact of relay 933, lower left hand contact of sequence switch spring 971, brush 944, commutator 948, upper left hand contact of sequence switch spring 967, upper left hand contact of sequence switch spring 963, ring conductor 996, terminal 884, brush 881, upper right hand and lower left hand contacts of sequence switch spring 861, to the junction of this conductor with the conductor that connects to the armature of relay 870 through contacts of sequence switch spring 850.

It will be remembered that relay 870 is being held in an actuated position over the fundamental circuit and that relay 933 is being held in an actuated position from the ground connected to the armature of relay 870. When the counting relays have been operated to the point of opening the fundamental circuit by the proper number of operations of the stepping relay, relay 870 is deenergized thus causing relay 933 to be deenergized. The deenergization of relay 870 removes the energizing circuit for updrive magnet 939 causing the switch elevator to be arrested in its upward movement, also an obvious circuit is established to move sequence switch 840 from position 8 to position 9.

The release of relay 933 establishes a circuit for energizing sequence switch magnet 960. This may be traced from grounded battery through the winding of sequence switch magnet 960, lower right hand and upper left hand contacts of sequence switch spring 961, to ground through the left hand spring and armature of relay 933, thus the sequence switch 960 is moved from position 2 to position 3.

When the counting relays shown in Fig. 5 are released the fundamental circuit is again established to again operate relay 870. Relay 870 in attracting its outer right hand armature establishes a circuit through the upper and lower right hand contacts of sequence switch spring 855 for energizing the sequence switch magnet 840 to move the sequence switch into position 10. A circuit is now established for operating relay 933. This may be traced from grounded battery through both windings of relay 933, upper left hand contact of sequence switch spring 964, conductor 995, terminal 885, brush 882, lower contacts of sequence switch spring 862, to ground through outer right hand spring and armature of relay 870. The actuation of relay 933 establishes a circuit for moving sequence switch 960 from position 3 to position 4. This path may be

130

traced from grounded battery, through the winding of magnet 960, right hand contacts of sequence switch spring 961, to ground through left hand contact and armature of relay 933.

5 In positions 3 and 4 a circuit is established for actuating trip magnet 936. This may be traced from grounded battery through the winding of trip magnet 936, 10 lower right hand contact of sequence switch spring 966, to ground. The actuation of the trip magnet 936 causes the brushes 973, 15 974, and 975 to be released for engagement with the bank terminals in a manner well known in the art, upon a subsequent upward movement of the switch elevator.

In position 4 of sequence switch 960, a circuit is established for actuating the up-drive magnet 939 for tens selection. This 20 path may be traced from grounded battery through the winding of updrive magnet 939, upper right hand and lower left hand contacts of sequence switch spring 962, right hand contacts and armature of relay 25 933, upper right contact of sequence switch spring 964, conductor 995, terminal 885, brush 882, lower contacts of sequence switch spring 862, to ground through the outer right hand contact and armature of relay 30 870.

The energization of the updrive magnet 939 causes the upward movement of the selector switch elevator bringing brush 943 into engagement with commutator 949. 35 again establishing a shunt path to intermittently deenergize the stepping relay 916. This shunt path may be traced from ground, through the left hand armature and contact of relay 933, lower left hand 40 contact of sequence switch spring 971, brush 943, commutator 949, lower right hand and upper left hand contacts of sequence switch spring 963, conductor 996, terminal 884, brush 881, upper right hand and lower left 45 hand contacts of sequence switch spring 861 to the junction with conductor 507 as previously described.

It should be noted that relay 933 is held in an actuated position over its locking circuit to ground connected to the armature of relay 870 previously traced. Upon the operation of a predetermined number of counting relays, the fundamental circuit is opened by the operation of relay 915, shown 55 in Fig. 5 and relay 870 is deenergized thus causing relay 933 to be deenergized. The release of relay 870 opens the actuating circuit for updrive magnet 939 causing the switch elevator to be arrested in its upward 60 movement. An obvious circuit is also established to move sequence switch 840 from position 10 to position 11. The release of relay 933 establishes a circuit for moving sequence switch 960 from position 65 4 to position 5. This may be traced from

grounded battery, through winding of sequence switch magnet 960, lower right hand and upper left hand contacts of sequence switch spring 961, to ground through left hand armature and contact of relay 933.

70 The fundamental circuit is again established with the sequence switch 960 resting in position 5 and sequence switch 840 in position 11 and relay 870 is reoperated. The operation of relay 870 establishes an operating circuit for relay 933 as previously traced, also a circuit through sequence switch spring 855 for energizing magnet 840 to move the sequence switch from position 11 to position 12. The operation of relay 933 establishes a circuit for moving sequence switch 960 from position 5 to position 6. This circuit may be traced from grounded battery, through the winding of magnet 960, right hand contacts of sequence 85 switch spring 961 to ground through the left hand spring and armature of relay 933.

85 Relay 933 is now held in an operated position over the holding circuit as previously described and a circuit is established through its right hand contact and armature for energizing the slow-speed updrive magnet 938. This circuit may be traced from grounded battery, through the winding of the slow-speed magnet 938, lower contacts 90 of sequence switch spring 962, right hand contact and armature of relay 933, upper right hand contact of sequence switch spring 964, conductor 995, terminal 885, brush 882, lower contacts of sequence switch spring 862, to ground, through the outer right hand contact and armature of relay 870. The elevator of the final selector switch is thus driven upward and brush 944 intermittently engages the metal portions of commutator segment 948 to intermittently deenergize the stepping relay 916 shown in Fig. 5. The shunt path for intermittently deenergizing the stepping relay may be traced from ground, through the left hand contact of relay 933, lower left hand contact of sequence switch spring 971, brush 944, commutator 948, upper left hand contact of sequence switch spring 967, upper left hand contact of sequence switch spring 963, conductor 996, terminal 884, brush 881, upper right hand and lower left hand contacts of sequence switch spring 861, to the junction point where this conductor joins the conductor connected to the armature of relay 110 105 110 115 120 125 130

120 125 130

877 through the contacts of sequence switch spring 850. When the counting relays have been energized for units selection, the fundamental will again be opened to release relay 870 which will open the energizing circuit for slow speed updrive magnet 938. The release of relay 870 also establishes a path for causing sequence switch 840 to move from position 12 to position 13. This path may be traced from grounded battery

through the winding of magnet 840, lower right hand and upper left hand contacts of sequence switch spring 855, to ground, through outer right hand contact and armature of relay 870. The release of relay 933 establishes a path for moving sequence switch 960 from position 6 to position 7. This path may be traced from grounded battery, through the winding of magnet 960, lower right hand and upper left hand contacts of sequence switch spring 961, to ground, through the left hand spring and armature of relay 933.

The selections controlled by the sender shown in Figs. 4 and 5 have now been completed. As will be recalled at this point in the operation certain of the relays in the connecting link are now operated and certain of the relays are released. One of the relays released is relay 505, assuming that plug 265 has been inserted in jack 267. Under these conditions relay 502 has been operated and now remains in a locked condition.

With relay 505 released, relay 502 operated plug 265 inserted in jack 267 and sequence switch 840 in position 13. A circuit is established for relay 872. This circuit may be traced from ground through the upper right winding of repeating coil 290, tip contacts of plug 265 and jack 267, outer left hand front contact of relay 502, outer right back contact of relay 508, conductor 507, the upper left hand winding of repeating coil 848, winding of relay 872 to battery at the lower contact of sequence switch spring 857. Relay 872 operates and closes a locking circuit for itself extending from battery over the lower contact of spring 857, winding of relay 872, upper contact of spring 853, left hand contact of relay 872, lower left and upper right hand contacts of sequence switch spring 859, left hand winding of relay 877 to ground over the upper left and lower right hand contacts of sequence switch spring 866. Relay 877 operates and locks over its right hand winding, lower contact of sequence switch spring 860, its right front contact to ground at the upper right contact of sequence switch spring 867 and establishes a circuit in parallel with its locking circuit through the winding of relay 871 to battery through the lower contact of sequence switch spring 852. Relay 871 at its left front contact establishes a circuit for relay 870 extending from battery, lower contact of sequence switch spring 852, winding of relay 870 to ground over the left contacts of sequence switch spring 851. With relay 870 operated a circuit is established for sequence switch magnet 840 extending from battery through the winding of magnet 840, the right hand contacts of sequence switch spring 855 to ground at the outer right front

contact of relay 870, thereby advancing the sequence switch into position 15. In position 15 the locking circuit of relay 877 is opened and this relay releases, in turn releasing relay 871.

With the incoming selector shown in Fig. 8, in position 15 a circuit is established for operating relay 933. This may be traced from ground, the upper right hand winding of repeating coil 848, upper normal contact and armature of relay 876, upper left hand and lower right hand contacts of sequence switch spring 862, brush 882, terminal 883, conductor 995, upper left hand contact of sequence switch spring 964, both windings of relay 933 to battery. Relay 933 in attracting its left hand armature establishes a circuit for moving sequence switch 960 from position 7 to position 8. This circuit may be traced from grounded battery, through winding of sequence switch magnet 960, right hand contacts of sequence switch spring 961 and armature of relay 933, to ground. When the sequence switch is passing from position 7 to position 8, relay 933 is released on account of its actuating path having been opened.

With sequence switch 960 in position 8, the wanted line is tested to ascertain whether it is idle or busy. A busy line is characterized by a ground connected to terminal 978 and an idle line is characterized by grounded battery connected to this same terminal. If the wanted line is busy, a circuit is established for actuating relay 933 which may be traced from grounded battery, through both windings of relay 933, lower left hand contact of sequence switch spring 963, lower right hand contact of sequence switch spring 967 to ground through normal spring and armature of relay 935. The actuation of relay 933 establishes a path for operating sequence switch 960 which may be traced from grounded battery, through winding of sequence switch magnet 960, right hand contacts of sequence switch spring 961, to ground through contact and armature of relay 933. The sequence switch is thus driven to position 14 where it energizes the down-drive magnet and connects the busy tone to the line as is well known in the art.

Assuming that the wanted line is idle, a circuit is established for relay 935 from battery on test terminal 978, brush 975, contact of spring 972, left winding of relay 935, lower contacts of spring 970, right winding of relay 935 to ground. The operation of relay 935 establishes a circuit for moving sequence switch 960 into talking position 16. This path may be traced from grounded battery, through the winding of sequence switch magnet 960, lower right contact of sequence switch spring 965, to ground, through right hand contact and armature of relay 935. It should be noted that relay 935

when operating, establishes a locking circuit for itself over its left hand armatures to the sleeve terminal 978. Since this path extends through the left hand low resistance winding of relay 935 the sleeve terminal is thus maintained busy until the selector switch moves out of talking position 16.

With sequence switch 840 in position 15 new circuits are established for holding relays 870 and 872 operated. The path for operating relay 870 may be traced from grounded battery, through the lower right hand winding of repeating coil 290, through the supervisory relay and key contacts of cord circuit 112, ring conductor of plug 265, ring of jack 267, inner left hand contacts of relay 502, inner left hand normal contacts of relay 505, conductor 508, left hand contacts of sequence switch spring 854, left hand normal contacts of relay 871, winding of relay 870, to ground through left hand contacts of sequence switch spring 851. The circuit for operating relay 872 may be traced from ground, through upper right hand winding of repeating coil 290, contacts of keys of cord circuit 112, tip of plug 265, tip of jack 267, outer left hand armature and contacts of relay 502, outer left hand normal contact and armature of relay 505, conductor 507, upper left hand winding of repeating coil 868, winding of relay 872, left hand contacts of sequence switch spring 856, inner contact of relay 870, upper contact of sequence switch spring 857 to battery.

In position 15 a circuit is established for operating relay 876. This circuit may be traced from grounded battery, through lower contact of sequence switch spring 853, contact and armature of relay 872, upper contacts of sequence switch spring 852, winding of relay 876, normal contact and armature of relay 875, normal contact and armature of relay 874, to ground, through normal contact and armature of relay 877. Relay 876 in operating establishes a circuit for the connection of ringing current to the ring conductor for the purpose of ringing the subscriber's station dialed. This may be traced from the ringing current source, through the right hand winding of relay 874, right hand contact of sequence switch spring 869, lower contact and armature of relay 876, upper contacts of sequence switch spring 861, brush 881, terminal 884, conductor 996, upper contacts of sequence switch spring 963, brush 974, terminal 977, over the line conductor to the subscriber's station apparatus. A ground for a return path is connected to tip conductor, through the upper contact and armature of relay 876, upper left hand and right hand contacts of sequence switch spring 862, brush 882, terminal 885, conductor 995, lower right hand contact of sequence switch spring 964, brush

973, terminal 976, to line conductor and subscriber's station apparatus.

The remaining operation of these selectors is well established in the art and it is therefore thought unnecessary to cover it in this description. It is thought that the preceding description of the operation of the incoming selector switch and final selector switch shown in Figs. 8 and 9 will enable a clear understanding of the release of such selectors when a call has been abandoned with insufficient digit keys actuated to connect the final selector switch Fig. 9 to the wanted line.

Let it be assumed that the operator has depressed the office key 114 and a digit key for the first numerical digit. The office key 114 actuates the allotter to select and control a connecting link to select an idle trunk and idle sender and associate them with the operator's position, including the indicating of the trunk number before the operator. One actuation of a digit key operates counting relays 704 and 705 of Fig. 4 as will be remembered from the previous description. Again let it be assumed that this registration has been carried forward to the point of actuating the incoming selector switch shown on Fig. 8. This would cause the actuation of relays 901 and 902 shown on Fig. 5. Stepping relay 916 is intermittently operated and released from the upward movement of the selector switch elevator, thus operating a given number of the counting relays effective for opening the fundamental circuit. When the relays 915 and O' have been operated, the shunt path is removed from the winding of relay 917 and it is therefore operated in series with the counting relays. Relay 917 is thereafter held in an operated position from grounded battery, through its right hand winding, right hand inner normal contact of relay 922, left hand outer contact and armature of relay 901, to ground through right hand contact and armature of relay 706. The absence of a second digit causes relay 706 to remain deenergized.

Relay 917 in attracting its left hand armature establishes an obvious circuit for actuating relay 900 which releases the counting relays and holds the fundamental circuit open as previously described. Relay 917 in attracting its right hand middle armature establishes an obvious circuit for actuating the dash-pot relay 919. Relay 919 is very slow to operate in order to allow time for the operator to actuate other digit keys.

Since it has been assumed that no other digits will be registered, relay 919 is operated after said given time interval establishing an obvious circuit for operating relay 922. The outer left hand armature and contact of relay 922 establish a holding cir-

cuit for relay 413. The middle left hand armature and contact of relay 922 are not effective at this time. The innermost left hand armature and contact establish a locking circuit for relay 922 which may be traced from grounded battery, through the winding and contacts of relay 922 to ground through the contact and armature of relay 918. The inner right hand armature and contact of relay 922, being opened, causes the release of relays 917 and 919. The outer right hand armature and contact of relay 922 establishes a circuit for operating relay 701 traced from grounded battery through its winding, conductor 735 to ground through armature and contact of relay 922. The operation of relay 701 releases certain connecting link apparatus which will be later described. The middle right hand contact and armature of relay 922 establish an obvious circuit for operating relay 921 which in turn establishes an actuating circuit for relay 920. This circuit may be traced from grounded battery, through winding of said relay, inner left hand armature and contact of relay 921 to ground through contact and armature of relay 918. The right hand contact and armature of relay 921 are not effective at this time.

30 The release of relay 917 and the operation of relays 920 and 921 establish a circuit to release the incoming selector of Fig. 8. This circuit may be traced from ground, through the left hand armature and contact of relay 705, left hand normal armature and contact of relay 917, outer left hand contact and armature of relay 921, left hand contact and armature of relay 920, outer left hand contact and armature of relay 704, conductor 621, brush 433 and its associated contact, upper contact and armature of relay 422, brush 430 and its associated contact, conductor 447, right hand outer contact and armature of relay 505, conductor 507, upper 45 left hand and lower right hand contacts of sequence switch spring 850, winding of line relay 870, normal contacts of relay 871, lower contacts of sequence switch spring 854, to grounded battery thus operating relay 50 870.

55 The operation of relay 870 will establish a circuit for actuating sequence switch magnet 840 through the right hand contacts of sequence switch 855. The sequence switch will thus rotate to the next selection position 4. Relay 870 is retained in an actuated position due to the establishment of its holding path. This holding path may be traced from grounded battery, through the 60 lower contacts of sequence switch spring 854, left hand normal contacts of relay 871, winding of line relay 870, upper contacts of sequence switch spring 851, inner contact and armature of relay 870, upper contacts 65 of sequence switch spring 850, and thence

to ground over the tip conductor of the trunk as previously traced for operating relay 870.

The up-drive magnet of the selector switch elevator is now energized over a path through the contacts of relay 870. This may be traced from grounded battery, through up-drive magnet 842, upper right hand and lower left hand contacts of sequence switch 862, to ground through the outer right hand contact and armature of relay 870.

70 Since the stepping relay 916 is not connected in this circuit, the selector switch brushes engaging with the segments 891, 892, 893 and 894 of the commutator will not have any effect upon the operation. The elevator will therefore continue in an upward movement until brush 889 is engaged with commutator 895 where a circuit is established for actuating the sequence switch magnet 840. This circuit may be traced from ground, through lower right hand contact of sequence switch spring 866, brush 889, commutator 895, upper right hand and lower left hand contacts of sequence switch spring 864, winding of sequence switch magnet 840, to battery. The sequence switch is thus rotated to position 6 where the circuit traced is opened at sequence switch spring 866. The following circuit is established for moving sequence switch 840 from position 6 to position 7: Grounded battery, through the winding of sequence switch magnet 840, right hand contacts of sequence switch spring 858, to ground, through left hand normal contact and armature of relay 877. In position 7 the circuit through sequence switch spring 866 is again established to energize the sequence switch magnet and rotate the sequence switch to position 17. It should be noted that the sequence switch in rotating opened the actuating circuit for relay 870 causing its release. In position 17 a circuit is established for energizing sequence switch magnet 840 from ground, through the armature and back contact of relay 870, upper left hand and lower right hand contacts of sequence switch spring 855, winding of sequence switch magnet 840, to grounded battery. The sequence switch is thus rotated to position 18 where an obvious circuit is established for actuating the downdrive magnet 841. The actuation of the downdrive magnet 841 lowers the selector switch elevator to its normal position and brings brush 889 into engagement with commutator 890 establishing a circuit to restore sequence switch 840 to its normal position. This circuit may be traced from ground through lower right hand contact of sequence switch spring 866, brush 889, commutator segment 890, lower right hand contact of sequence switch spring 863, winding of sequence switch magnet 840 130

to grounded battery. Relay 918 will have operated before incoming selector switch, Fig. 8, restores to its normal position, causing the release of relay 920 to open the circuit established for the original operation of relay 870. This will prevent again driving the incoming selector out of its normal position. The release of the sender apparatus including relay 920 will hereinafter be described in detail.

Release of incoming and final selector switches

Let it be assumed that the operator has 15 depressed the office key 114 and the digit keys a sufficient number of times to accomplish selections in both the incoming selector, Fig. 8, and final selector, Fig. 9, the number of digit keys depressed, however, not 20 being sufficient to carry the final selector, Fig. 9, forward to a point of connection with a subscriber's line. The circuit shown 25 in Fig. 5 and described for releasing the incoming selector switch, Fig. 8, is also adapted to release the incoming selector and thus the final selector under the condition described above.

The actuation of the office key 114 actuates the apparatus of the connecting link to 30 control it to select an idle trunk, an idle sender and associate them with the operator's position, including the actuation of apparatus to indicate the trunk number before the operator.

35 Let it be assumed that the actuation of the digit keys operate the following relays in the sender to set up the desired condition, relays 704, 705, 706, 707, 708, 709 and the associated register relays according to the 40 digit keys actuated. Also relays 901, 902, 903, 905, 906, 907, 908 and 909.

It will be remembered that the operation 45 and release of relay 917 takes place after each series of operations of the counting relays. However, when the complete number of digits is not sent forward, relay 917 will be operated when the last digit is registered but will not be released. In the condition just assumed for the sender apparatus, the 50 holding circuit for relay 917 may be traced from grounded battery through the right hand winding of relay 917, inner right hand contact and armature of relay 922, outer left hand armature and contact of relay 908 to 55 ground through the contact and armature of relay 710.

Since relay 917 is held operated, circuits are established for the operation of relays 919, 922, 921, 920 and 701 as covered under 60 the description for releasing incoming selector, Fig. 8. The releasing of relay 917 after the operation of relay 922 and the operation of relays 920 and 921 establishes a circuit to release the incoming selector, Fig. 8. 65 This circuit may be traced from ground

through the left hand armature and contact of relay 705, left hand normal armature and contact of relay 917, outer left hand contact and armature of relay 921, left hand contact and armature of relay 920, outer 70 left hand contact and armature of relay 704, conductor 621, brush 433 and its associated contact, upper contact and armature of relay 422, brush 430 and its associated contact, conductor 447, right hand outer contact and armature of relay 505, conductor 507, upper left hand winding of repeating coil 848, winding of relay 872, lower left hand contact of sequence switch spring 857 to grounded battery, operating marginal re- 75 lay 872.

It will be remembered from the detailed description of the incoming selector that the sequence switch is in one of the positions between 8 to 12 when the final selector 85 switch, Fig. 9, is being controlled from the sender shown in Figs. 4 and 5. The operation of relay 872, therefore, establishes a circuit for updrive magnet 842. This may be traced from grounded battery through 90 winding of updrive magnet 842, right hand contact and armature of relay 872 to ground through lower left hand contact of sequence switch spring 868.

The elevator of the selector switch will 95 now be driven in an upward movement until brush 889 is engaged with commutator 895. A circuit is thus established for actuating the sequence switch magnet 840. This circuit may be traced from ground through the 100 lower right hand contact of sequence switch spring 866, brush 889, commutator 895, upper right and lower left hand contacts of sequence switch spring 864, winding of sequence switch magnet 840 to battery. This 105 circuit remains established during the time that the sequence switch is moving to position 17. It should be noted that the sequence switch in rotating to this position opens the actuating circuit for relay 872 causing its release. In position 17 a circuit 110 is established for energizing sequence switch magnet 840 from ground through the armature and back contact of relay 870, upper left hand and lower right hand contacts of sequence switch spring 855, winding of sequence switch magnet 840 to grounded battery. The sequence switch is thus rotated to position 18, where an obvious circuit is established for actuating the downdrive 115 magnet 841. The actuation of the downdrive magnet 841 lowers the selector switch 120 elevator to its normal position and brings brush 889 into engagement with commutator 890, establishing a circuit to restore a sequence switch 840 to its normal position.

This circuit may be traced from ground 125 through the lower right hand contact of sequence switch spring 866, brush 889, commutator segment 890, lower right hand con- 130

tact of spring 863, winding of sequence switch magnet 840 to grounded battery.

Upon the downward movement of the incoming selector switch elevator, brushes 880, 881 and 882 are disengaged from terminals 883, 884 and 885 and the holding circuit for relay 934 is thus broken causing its release. The release of relay 934 establishes an energizing circuit for sequence switch magnet 960. This may be traced from grounded battery through the winding of sequence switch magnet 960, upper left hand contact of sequence switch spring 965 to ground through contact and armature of relay 934. This circuit remains established until the sequence switch arrives in position 14, where the circuit is established for energizing the downdrive magnet 937. This circuit may be traced from grounded battery through the winding of downdrive magnet 937, right hand contacts of sequence switch spring 969 to ground through contact and armature of relay 935.

The selector switch elevator is now lowered under the control of the down drive magnet 937 until it reaches its normal resting position where brush 945 is brought into engagement with commutator 946. A circuit is thus established for actuating sequence switch magnet 960, which may be traced from grounded battery through the winding of sequence switch magnet 960, lower left hand contact of sequence switch spring 965, commutator 946, brush 945 to ground through upper left hand contact of sequence switch spring 971. The actuating circuit traced causes sequence switch 960 to rotate from position 14 to position 15. In position 15 sequence switch magnet 960 is again energized through the upper left hand contact of sequence switch spring 965, contact and armature of relay 934 to ground. This energizing circuit remains established until the sequence switch is moved into position 18. In position 18 an energizing circuit for sequence switch magnet 960 is established from ground through the upper left hand contact of sequence switch spring 971, brush 945, commutator segment 946, lower left hand contact of sequence switch spring 965, winding of sequence switch magnet 960 to grounded battery. The sequence switch is thus driven into its normal position 1.

The incoming selector switch and final selector switch have now been restored to normal and may be used for other service connections.

60 Release of connecting link

A part of the connecting link apparatus is released at the same time that the selector switch or switches are being restored to normal. The operation of relay 701 as previously described establishes a circuit for

operating relay 877. This circuit may be traced from grounded battery through winding of relay 877, conductor 452, brush 456 and its associated terminal, conductor 624, inner right hand armature and contact of relay 701, outer right armature and contact of relay 922 to ground. The operation of relay 877 establishes a circuit for releasing the apparatus associated with the operator's position. The restoration begins with the energization of relay 406 over a circuit from ground through the contact and armature of relay 877, right hand winding of relay 406 to grounded battery. The energization of relay 406 opens the locking circuit for relay 305 and as relay 305 deenergizes the holding circuit for relays 207, 205 and 313 is broken. These relays are deenergized due to the fact that relay 206 has remained energized and the original locking circuit for these relays has been broken at the left hand armature and back contact of relay 206. The deenergization of relay 205 opens the energizing circuit for exchange lamp 208 and the original energizing circuit of relay 301. The deenergization of relay 207 opens the locking circuit for the various relays of the trunk indicator and all of these relays are released. The deenergization of relay 313 opens the circuit for relay 320. The deenergization of relays 205 and 313 opens the circuit paths connected to the bridge circuit of a lotter 121.

During the latter part of the release of the incoming selector switch and after the proper time interval, relay 918 is operated by the actuating circuit connected through its winding. The operation of relay 918 establishes a holding circuit for relay 701 and opens the energizing circuits for relays 922 and 920 to cause their release. The deenergization of relay 922 opens the energizing circuit for relay 921. The actuation of relay 918 opens the holding circuit for the register relays of the sender, Figs. 4 and 5.

Since relay 922 has deenergized and relay 701 remains energized from the contact of slow releasing relay 918, the holding circuit for relay 413 is now opened and therefore this relay will release. The middle right-hand contact of relay 922 establishes a circuit for maintaining the sender busy until such time as relays 918 and 701 are released which circuit may be traced from ground through the middle right hand armature and contact of relay 922, left-hand armature and contact of relay 701 to conductor 625.

The deenergization of relay 413 opens the energizing path for relays 405, 420 and 316. The deenergization of relay 405 causes the deenergization of relays 415 and 410, and also breaks the original operating circuit for switch magnet 408. The deenergization of relay 415 opens the energizing cir-

cuit for relay 417 and the operating circuit for trunk selecting magnet 416. The deenergization of relay 415 also removes the ground from conductor 350 that has been connected to the allotter 121 to retain it in a busy condition. This connecting link may therefore again be seized by the allotter.

Abandoned calls, no digit keys actuated

10 Let it be assumed that the operator in an office using this type of apparatus has depressed the office key 114 when the calling subscriber abandons the call and that the operator does not actuate any of the 15 digit keys.

13 The actuation of the office key 114 actuates an allotter relay 301 to control a connecting link in its selection of a trunk and sender selector. The apparatus of the connecting link will thus be actuated to associate said trunk with the operator's position and indicate the trunk number before the operator. Since no digit keys have been actuated, the register apparatus of the sender is not actuated. The detail operation of the connecting link apparatus is thought to be well understood from the preceding description and therefore will not now be covered in detail.

30 A means for releasing connecting link apparatus actuated on an abandoned call of this kind is shown in Figs. 4 and 5. The initial actuation of this apparatus occurs immediately upon the association of the 35 connecting link with the sender. The circuit for this actuation may be traced from ground through the winding of relay 413, left hand contact and armature of relay 410, switch arm 425 and its associated contact, 40 conductor 625, winding of relay 702, right hand outer normal contact and armature of relay 701 to grounded battery. Relays 702 and 413 are actuated in this circuit. The utility of relay 413 has been previously 45 described and therefore will not be covered in this description. Relay 702 in attracting its armature and contact establishes a circuit for actuating relay 919 which may be traced from grounded battery 50 through the winding of relay 919, conductor 993, armature and contact of relay 702 to ground through the inner right hand normal contact and armature of relays 704. Relay 919 is a slow operating dash pot relay used 55 to allow a period of time for delayed operation of the digit keys. Should a digit key be operated preceding the operation of relay 919, the actuation of relay 704 would take place and, therefore, the actuating circuit for relay 919 would be opened. It is 60 assumed in this description that no digit keys are depressed, and therefore relay 704 remains deenergized. The operation of relay 919 establishes an obvious circuit for 65 operating relay 922. The outer right hand

contacts of relay 922 establish a circuit for operating relay 701 which may be traced from grounded battery through the winding of relay 701, conductor 735 to ground through the armature and contact of relay 922. Relay 922 in attracting its right hand middle armature establishes an obvious circuit for operating relay 921 and in attracting its inner left hand armature establishes a locking circuit for itself to ground through the contact and armature of relay 918. The operation of relay 921 establishes a circuit for operating relay 920 which may be traced from grounded battery through the winding of relay 920, inner left hand armature and contact of relay 921 to ground through contact and armature of relay 918. The outer left hand contacts and the right hand contacts of relay 921 are not effective in this operation. Relay 920 in operating establishes an obvious circuit through the winding of relay 918. This relay is, however, very slow in operating to allow time for the restoration of the link apparatus.

The operation of relay 701, as previously described, opens the circuit for relay 702 which releases. The release of relay 702 opens the circuit for relay 919 causing it to release. The inner right hand contacts of relay 701 establish a circuit for operating relay 377 to release part of the apparatus in the link. This circuit may be traced from grounded battery through the winding of relay 377, conductor 452, switch arm 456 and associated contact, conductor 624, armature and contact of relay 701, conductor 735 to ground through the outer right hand armature and contact of relay 922. 90 95 100

The operation of relay 377 establishes a circuit for energizing relay 406 over a circuit from ground through the contact and armature of relay 377, right hand winding of relay 406 to grounded battery. The energization of relay 406 opens the locking circuit for relay 305 and as relay 305 deenergizes, the holding circuit for relays 207, 205 and 313 is broken. These relays are deenergized due to the fact that relay 206 has remained energized and the original locking circuit for these relays has been broken at the left hand armature and back contact of relay 206. The deenergization of relay 205 opens the energizing circuit for the exchange lamp 208 and the original energizing circuit for relay 301. The deenergization of relay 207 opens the locking circuit for the various relays of the truck indicator and all of these relays are released. The deenergization of relay 313 opens the circuit for relay 320. The deenergization of relays 305 and 313 opens the circuit paths connected to the bridge circuit of the allotter 121.

After the proper time interval, relay 918 is operated establishing a holding circuit for relay 701 and opens the energizing circuit 130.

cuits for relays 922 and 920 to cause their release. The deenergization of relay 922 opens the energizing circuit relay 921.

It should be noted that the operation of relay 922 established a supplemental holding circuit for relay 413. Since relay 922 has been deenergized and relay 701 remains energized from the contact of slow releasing relay 918, the holding circuit for relay 413 is now opened and therefore this relay will release. The middle right hand contacts of relay 922 establish a circuit for maintaining the sender busy until such time as relays 918 and 701 are released. This circuit may be traced from ground through the middle right hand armature and contact of relay 922, left hand armature and contact of relay 701 to conductor 625.

The deenergization of relay 413 opens the energizing path for relays 405, 420 and 316. The deenergization of relay 405 causes the deenergization of relays 415 and 410 and also breaks the original operating circuit for switch magnet 408. The deenergization of relay 415 opens the energizing circuit for relay 417 and the operating circuit for trunk selecting magnet 416. The deenergization of relay 415 also removes the ground from conductor 350 that has been connected to the allotter 121 to retain it in a busy condition. This connecting link may therefore be seized by the allotter.

What is claimed is:

1. In an automatic telephone exchange system, a plurality of operators' positions, trunk selector switches common to said operators' positions, indicating devices individual to each operator's position, means under the control of any one of said operators to put an idle trunk selecting switch into operation, and means to operate the indicating devices at said operator's position in accordance with the position assumed by said trunk selecting switch.

2. In an automatic telephone exchange system, a plurality of operators' positions, a plurality of outgoing trunks, automatic means under the control of an operator to select one of said outgoing trunks, a variably operable trunk indicator individual to each operator's position, an impulse sending device, means operated in accordance with the selection of said trunk to transmit impulses to a particular one of said trunk indicators, and means in said indicator responsive to said impulses to indicate to said operator the number of the trunk selected.

3. In a telephone exchange system, a plurality of operators' positions, a plurality of outgoing trunks each trunk terminating at its distant end in an automatic switch, means under the control of an operator to select one of said outgoing trunks, a variably operable indicator individual to each operator's position, means to indicate a plurality

of digits in a trunk number, and means to selectively control the indication of each digit of the number in accordance with the trunk selected.

4. In a telephone exchange system, a plurality of operators' positions, a plurality of outgoing trunks each trunk terminating in its distant end in an automatic switch, means under the control of an operator to select one of said outgoing trunks, a variably operating trunk indicator individual to each operator's position, a common impulse sending device, means operated in accordance with the selection of said trunk to transmit impulses to a particular one of said trunk indicators, and means in said indicator responsive to said impulses to indicate to said operator the number of the trunk selected, means to indicate a plurality of digits in a trunk number, and means to selectively control each digit of the number to be indicated in accordance with the trunk selected. 70 75 80 85

5. In a telephone exchange system, a plurality of operators' positions, a sender controlling equipment at each of said positions, a plurality of outgoing trunks, each trunk terminating at its distant end in an automatic switch, a plurality of sending devices, a plurality of connecting units common to said operators' positions, means to operate a connecting unit to establish an interconnection between a sender controlling equipment, a sender and an idle trunk, means to indicate to an operator the number of the idle trunk selected, and means to operate an automatic switch over said trunk under the control of a sender in accordance with the operation of said sender controlling equipment. 90 95 100

6. In a telephone exchange system, a plurality of operators' positions, a plurality of sending devices common to said operators' positions, a plurality of groups of outgoing trunks terminating in automatic switches, an allotter switch individual to each of said groups of outgoing trunks, a plurality of connecting units controlled by said allotter switch, each connecting unit comprising a trunk finder switch, a sender selector switch and an operator's position finder, means to operate the connecting unit to associate a sending device with an operator's position and with an idle outgoing trunk, means to operate automatic switches over said trunk, and means to indicate to the operator the number of the trunk selected. 105 110 115 120

7. In a telephone exchange system, a plurality of operators' positions, a sender controlling equipment at each of said positions, a plurality of groups of outgoing trunks, each trunk terminating at its distant end in an automatic switch, a plurality of common connecting units, each unit comprising a trunk finder, a sender selector and an opera- 125 130

- 5 tor's position finder, means to operate the connecting unit to find an idle trunk, to select an idle sender, and to associate said sender with an operator's position, means to indicate to the operator the number of the outgoing trunk selected, and means under the control of said operator's sender controlling equipment to adjust said sender to cause automatic selective operations of the switch at the distant end of the selected trunk. 10
- 10 8. In an automatic telephone exchange system, a plurality of operators' positions, a plurality of outgoing trunks appearing in multiple jacks at said positions, a number indicator individual to each of said positions and common to the trunks outgoing from each position, automatic means to select an idle trunk, and means common to said positions to operate an indicator individual to an operator's position to visually display the number of the trunk selected. 15
- 20 9. In an automatic telephone exchange system, a plurality of operators' positions, a plurality of outgoing trunks appearing in multiple jacks at said positions, a number indicator individual to each of said positions and common to the trunks outgoing from each position, automatic means to select an idle trunk, and a common impulse sending device to control a desired one of said number indicators. 25
- 30 10. In a telephone exchange system, a plurality of switching devices, a controlling circuit for said switching devices, means to successively operate said switching devices in response to current impulses over said controlling circuit and a set of counting relays functioning as an auxiliary switch to control the successive association of said controlling circuit with said switching devices. 35
- 40 11. In a telephone exchange system, automatic switches, means to control said automatic switches including a controlling device, a registering device, and a sending device, a set of counting relays associated with said registering device to act as a progression switch to control the successive association of said registering devices with said controlling device, and a second set of counting relays operating as a progression switch for controlling the successive operations of said sending device. 45
- 50 12. In a telephone exchange system, a number indicating device, an impulse sending device including a plurality of rotatable contacts, a brush set, certain of said brushes being identified with certain numerical designations, and certain others of said brushes being utilized for the sending of impulses for the control of said indicator, and a circuit arrangement such that said impulse controlling brushes may also be utilized in identifying certain numbers. 55
- 60 13. In a telephone exchange system, in combination, incoming lines, outgoing trunks, an operator's position, a cord circuit terminating at each end in a manually operable device for interconnecting an incoming line and an outgoing trunk under the control of said operator's position, switching devices at the distant end of the said trunks, automatic means for controlling said switching devices over said trunks independent of said operator's position, and means at said operator's position to control the automatic selection of a trunk and variably control the setting of said automatic means for controlling said switching devices over said trunk. 70
- 75 14. In a telephone exchange system, in combination, incoming lines, outgoing trunks, an operator's position, a cord circuit for interconnecting an incoming line and an outgoing trunk under the control of said operator, switching devices at the distant end of said trunks, a variably operable sender for controlling said devices over said trunks and normally disassociated therefrom, a variably adjustable controlling device for said sender at said operator's position, means for associating said sender with an idle trunk, and means for connecting the controlling leads of said sender with the leads of the chosen trunk depending for its operation on the finding of an idle trunk. 80
- 85 15. In a telephone exchange system, in combination, incoming lines, outgoing trunks, a cord circuit for interconnecting an incoming line and an outgoing trunk, switching devices at the distant end of said trunks, a plurality of variably operable senders for controlling said devices over said trunks normally disconnected therefrom, a variably adjustable controlling device for said senders normally disconnected therefrom, means for associating said controlling device with an idle sender, means for associating said idle sender with an idle trunk, and a common starting circuit for said two associating means. 90
- 95 16. In a telephone system, in combination, incoming lines, outgoing trunks, a cord circuit for interconnecting an incoming line and an outgoing trunk, switching devices at the distant end of said trunks, a plurality of variably operable senders for controlling said devices over said trunks normally disconnected therefrom, a variably adjustable controlling device for said senders normally disconnected therefrom, a plurality of connecting units each comprising a switching means for associating the unit with the controlling device, switching means for associating the unit with an idle sender, and a switching means for associating the unit with an idle trunk. 100
- 105 17. In a telephone exchange system, in combination, incoming lines, outgoing trunks, a cord circuit for interconnecting an incoming line and an outgoing trunk, 110
- 115 120
- 125 130

switching devices at the distant end of said trunks, a plurality of variably operable senders for controlling said devices over said trunks normally disconnected therefrom, a variably adjustable controlling device for said senders normally disconnected therefrom, a connecting unit comprising a switching means for associating the unit with the controlling device, and common starting means for said switching means.

18. In a telephone system, in combination, incoming lines, outgoing trunks, a cord circuit for interconnecting an incoming line and an outgoing trunk, switching devices at the distant end of said trunks, a plurality of variably operable senders for controlling said devices over said trunks normally disconnected therefrom, a variably adjustable controlling device for said senders normally disconnected therefrom, a plurality of connecting units each comprising a switching means for associating the unit with the controlling device, and means for starting an idle connecting unit.

19. In a telephone exchange system, in combination, incoming lines, groups of outgoing trunks, a cord circuit terminating at each end in a manually operable device for interconnecting an incoming line and an outgoing trunk, switching devices at the distant end of said trunks, means associated with each group of trunks for variably controlling said devices over said trunks, and means for selecting any one of said controlling means.

20. In a telephone exchange system, in combination, incoming lines, groups of outgoing trunks, a cord circuit for interconnecting an incoming line and an outgoing trunk, switching devices at the distant end of said trunks, a plurality of means associated with each group of trunks for variably controlling said devices over said trunks, means for selecting any one of said groups of controlling means, and means for starting an idle controlling means in a selected group.

21. In a telephone exchange system, in combination, incoming lines, groups of outgoing trunks, groups of cord circuits terminating at each end in a manually operable device for interconnecting an incoming line and an outgoing trunk, switching devices at the distant end of said trunks, a variably adjustable controlling device associated with each group of cord circuits, a means associated with each group of trunks for selecting an idle trunk in said group and for selecting a controlling device, and a variably operable sender responsive to said controlling device and associated with said selecting means for controlling the switching device connected with the selected trunk.

22. In a telephone exchange system, in combination, incoming lines, groups of out-

going trunks, groups of cord circuits for interconnecting an incoming line and an outgoing trunk, switching devices at the distant end of said trunks, a variably adjustable controlling device associated with each group of cord circuits, a plurality of devices associated with each group of trunks for selecting an idle trunk in said group and for selecting a controlling device, and a variably operable responsive to a controlling device and associated with said selecting devices for controlling the switching device connected with the selected trunk.

23. In a telephone exchange system, in combination, a plurality of variably operable senders, a plurality of variably adjustable controlling devices for said senders, a plurality of trunk lines, a common selecting means for connecting together an idle sender, an idle trunk and a designated controlling device, and means for distinguishing the controlling device to permit it to be seized by the selecting means.

24. In a telephone system, in combination, a plurality of variably operable senders, a plurality of variably adjustable devices for controlling any of said senders, groups of outgoing lines, and means associated with each of said group of outgoing lines for selecting an idle line in said group, an idle sender and a designated controlling device and connecting them together.

25. In a telephone exchange system, in combination, a plurality of variably operable senders, a plurality of variably adjustable devices for controlling any of said senders, groups of outgoing lines, and a plurality of selecting means associated with each group of outgoing lines for connecting together an idle line in the group, an idle sender and a designated controlling device.

26. In a telephone exchange system, in combination, a plurality of variably operable senders, plurality of variably adjustable devices for controlling any of said senders, groups of outgoing lines, selecting means associated with each of said groups of outgoing lines for connecting together an idle line in said group, an idle sender and a designated controlling device, and means for distinguishing the controlling device to permit it to be seized by a selecting means.

27. In a telephone exchange system, in combination, a plurality of variably operable senders, a plurality of variably adjustable controlling devices for said senders, a plurality of outgoing lines, a selecting means for connecting together an idle line, an idle sender and a particular controlling device, and indicating means associated with a controlling device for displaying the designation of the chosen outgoing line.

28. In a telephone exchange system, in combination, a plurality of variably operable senders, a plurality of variably adjust-

- able controlling devices for said senders, groups of outgoing lines, a selecting means for each group of lines for connecting together an idle line in that group, an idle 5 sender and a particular controlling device, and indicating means associated with a controlling device for displaying the designation of a group of lines and the chosen line in said group.
- 10 29. In a telephone exchange system, in combination, a plurality of variably operable senders, a plurality of variably adjustable controlling devices for said senders, groups of outgoing lines, a group of 15 selecting means for each group of lines for connecting together an idle line in that group, an idle sender and a particular controlling device, means individual to each group for allotting an idle selecting means, 20 and indicating means associated with a controlling device for displaying the designation of the group of lines and the chosen line in said group.
30. In a telephone exchange system, in combination, a plurality of variably operable senders, a plurality of variably adjustable controlling devices for said senders, groups of outgoing lines, a group of selecting means for each group of lines for connecting together an idle line in that group, an idle sender and a particular controlling device, means individual to each group for allotting an idle selecting means, and indicating means associated with the controlling 35 device comprising means for displaying the designation of a group of lines and means for displaying the designation of a line in said group.
31. In an automatic telephone system, a plurality of operators' positions, a plurality of outgoing trunks extending to automatic switches in a given automatic telephone office, an allotter controlled from each of said plurality of operators' positions, automatic means controlled by said allotter to connect one of said trunks to any of said operators' positions and indicate the number of said trunk, and means connected to an operator's position to variably control the 40 automatic switches in said automatic office.
32. In an automatic telephone system, in combination, incoming lines, outgoing trunks, an allotter, a switching device under the control of said allotter, a trunk number indicating device common to said trunks, means to operate said allotter to control said switching device to automatically select an idle trunk and visually display its number upon said indicating device, and 45 means to make a service connection between one of said incoming lines and the outgoing trunk selected.
33. In an automatic telephone system, an allotter, a plurality of operators' positions, means at each operator's position for controlling said allotter, outgoing trunks, means in said allotter for controlling automatic selection of said outgoing trunks and means, when a plurality of operators' positions simultaneously operate said controlling means to successively connect idle outgoing trunks to said operators' positions and indicate the trunk number at the position to which each trunk is connected.
34. In a telephone system, a manual office including a plurality of operators' positions, an automatic office, a plurality of sets of disassociated units, an allotter controlled from each of said plurality of operators' positions, means under the control of said allotter to coordinate said disassociated units to produce a controlling device and to connect said controlling device into operative relation with an operator's position to complete a service connection from a subscriber in said manual office to a subscriber in said automatic office and means to successively connect said controlling devices to different operators' positions in turn when a plurality of operators simultaneously exercise control of said allotter.
35. In a telephone exchange system, a plurality of groups of trunks, a plurality of groups of automatic switches, each of said groups of switches having access to a particular group of trunks, a plurality of means for selecting any one of said switch groups and means for selective response to the simultaneous operation of said plurality of said group selecting means.
36. In a telephone exchange system, a plurality of groups of trunks, a plurality of groups of automatic switches, said switches being capable of movement in a single direction only, each of said groups of switches having access to a particular group of trunks, means for selecting any one of said switch groups and means to cause an idle switch in a desired group to hunt for and connect with an idle trunk in its corresponding trunk group.
37. In a telephone exchange system, a plurality of operators' positions, a sender controlling equipment at each of said positions, a plurality of trunks extending in a plurality of different directions, a plurality of sending devices, a plurality of connecting units common to said operators' positions, means to operate a connecting unit to establish an interconnection between the sender controlling equipment, a sender and an idle trunk extending in a desired direction, and means to indicate to an operator the number of the idle trunk selected.
38. In a telephone exchange system, a plurality of operators' positions, a plurality of sending devices common to said operators' positions, a plurality of groups of outgoing trunks, each group of trunks serving equipment separated from the equipment

- served by each other group, an allotter switch individual to each of said groups of outgoing trunks, a plurality of connecting units controlled by said allotter switch, each 5 connecting unit comprising a trunk finder switch, a sender selector switch and an operator's position finder, means to operate the connecting unit to associate a sending device with an operator's position and with an idle outgoing trunk in a desired group.
39. In an automatic telephone exchange system, a plurality of operators' positions, a number indicator individual to each of said positions, a plurality of trunks extending in a plurality of different directions, automatic means to select an idle trunk in a desired direction, and means common to said positions to operate an indicator individual to an operator's position to indicate the 10 number of the trunk selected.
40. In a telephone exchange system, in combination, incoming lines, outgoing trunks, an operator's position, a cord circuit terminating at each end in a manually 15 operable device for interconnecting an incoming line and an outgoing trunk under the control of said operator, switching devices at the distant end of said trunks, said switching devices being located at a plurality of offices, automatic means independent of said operator's position for controlling said switching device over said trunks, and means at said operator's position to control the automatic selection of a trunk to a 20 particular office and variably control the setting of said automatic means for controlling said switching devices over said trunk.
41. In a telephone exchange system, in combination, incoming lines, outgoing 25 trunks, an operator's position, a cord circuit at said operator's position for interconnecting an incoming line and an outgoing trunk, a switching device at the distant end of each of said trunks, said switching devices being located in separate offices, a variably operable sender for controlling 30 said switching devices over said trunks and normally disassociated therefrom, a variably adjustable controlling device for said sender, means for associating said sender with an idle trunk to any desired office, and means for connecting controlling leads of 35 said sender with the leads of the chosen trunk depending for its operation on the finding of an idle trunk to said desired office.
42. In a telephone exchange system, in combination, incoming lines, groups of outgoing trunks, a cord circuit terminating at 40 each end in a manually operable device for interconnecting an incoming line and an outgoing trunk, switching devices at the distant end of said trunks, each of said groups of trunks being associated with switching devices in a particular telephone office, 45 means associated with each group of trunks for variably controlling said switching device over said trunks, and means for selecting any one of said controlling means.
43. In an automatic telephone system, an operator's position, a plurality of outgoing trunks, automatic switches, a sender for controlling said automatic switches over said outgoing trunks, registers in said sender, a line, means at said operator's position to set said registers in accordance with the designation of a wanted line, and means in said sender to automatically release said automatic switches when a complete line designation is not recorded on the registers. 50
44. In an automatic telephone system, an operator's position, a plurality of outgoing trunks, automatic switches, a sender for controlling said automatic switches over said outgoing trunks, registers in said sender, a line, means at said operator's position to set said registers in accordance with the designation of a wanted line, and means in said sender to automatically release said automatic switches when a complete line designation is not recorded on the registers with 55 in a predetermined time period.
45. In an automatic telephone system, a manual office including operators' positions, an automatic office, selector switches in said 60 automatic office, a sender, register relays in said sender to automatically control said selector switches, a line, means at said operator's position controlling the setting of the register relays in accordance with the designation of the wanted line, and means in said sender to automatically release said selector switches when a complete line designation is not recorded on the registers. 65
46. In an automatic telephone system, a manual office including operators' positions, an automatic office, selector switches in said 70 automatic office, a sender registers in said sender to automatically control said selector switches, a line, means at said operator's position to control the setting of said registers in accordance with the designation of the wanted line, and means in said sender to automatically release said selector switches when a complete line designation is not recorded on the registers within a predetermined time period. 75
47. In an automatic telephone system, an operator's position, a plurality of outgoing trunks each connected to an automatic 80 switch, a line, an allotter controlled from said operator's position, a connecting unit automatically controlled by said allotter, a sender automatically selected by said connecting unit, a trunk circuit automatically selected by said connecting unit, means at said operator's position for controlling said allotter, means at said operator's position for controlling said automatic switches to select said line, and automatic means for releasing 85

- 5 said apparatus when said automatic switches are not directed to select said line.
48. In a telephone system, a call sender, a plurality of groups of trunk lines, a plurality of operator's devices, one for each of said groups of trunk lines, and an automatic switching mechanism responsive to the actuation of any one of said devices for connecting said sender to an idle trunk line in the group corresponding to the actuated device. 10
49. In a telephone system, a number storing device comprising groups of marginal and sensitive relays, each group of relays serving to store the designation of one digit, a single set of ten numerical keys, and means for successively and variably adjusting said groups of relays under the control of said set of keys. 15
50. In a telephone system, a plurality of operators' positions each of which is provided with a single set of ten numerical keys, a plurality of sets of number storing devices common to said operators' positions, means for associating an idle set of number storing devices with the key set of an operator's position, means for successively operating said set of keys for variably adjusting the associated set of number storing devices, and means selectively actuated by 20 said set of number storing devices.
51. In a telephone system, a plurality of operators' positions, each of which is provided with a single set of ten numerical keys, a plurality of register senders common to said operators' positions, each register sender comprising a plurality of groups of relays, means for associating an idle register sender with the key set of an operator's position, and switching means for each register whereby the repeated operation of a key set is effective to operate a different group of relays of the associated sender. 25
52. In a telephone system, a plurality of operators' positions, each of which is provided with a single set of ten numerical keys, a plurality of register senders common to said operators' positions, each register sender comprising a plurality of groups of relays of various degrees of electromagnetic sensitivity, means for associating an idle register sender with the key set of an operator's position, and switching means for each register whereby the repeated operation of a key set is effective to operate a different group of relays of the associated sender. 30
53. In a telephone system, a plurality of operators' positions, each of said positions being provided with a single strip of keys, a plurality of senders common to said operators' positions, each sender having a plurality of registers arranged to be successively operated by the repeated actuation of a strip of keys. 35
54. In a telephone operator's sender for controlling automatic switches, a plurality of storage devices each comprising a set of digit relays, the number of said storage devices being equal to the number of digits in the telephone numbers, a common set of digit keys, and a transfer relay in each storage device except the last for shifting the control of said keys from one storage device to the next. 40
55. In an operator's sender for controlling automatic switches, a plurality of storage devices each comprising a set of digit relays, a common set of digit keys, a transfer relay in each storage device for shifting the control of said keys from one storage device to the next, means for energizing a digit relay in one of said devices when a digit key is actuated, and means for energizing the transfer relay in said device when the actuated digit key is restored. 45
56. In an operator's sender, a set of digit keys, two relay storage devices, means for causing a relay in one storage device to respond to the actuation of a key in said set, a transfer relay responsive to the release of the said key, and means controlled by said transfer relay for rendering the relays of the second storage device responsive to the keys of said set. 50
57. In an operator's sender, a digit key, a digit relay responsive to the actuation of said key, a second digit relay non-responsive to the first actuation of said key, and a transfer relay responsive to the restoration of said key for rendering said second digit relay responsive to the second actuation of said key. 55
58. In an operator's sender, a digit key, a digit relay responsive to the actuation of said key, a second digit relay non-responsive to the first actuation of said key, a transfer relay responsive to the restoration of said key for rendering said second digit relay responsive to the second actuation of said key, and locking circuits for maintaining said digit relays energized independent of said key. 60
59. In an operator's sender, a digit key of the self-restoring type, said key remaining in operated position only so long as it is held manually, a digit relay responsive to the actuation of said key, a second digit relay normally non-responsive to said key, and a transfer relay responsive to the restoration of said key to normal for rendering said second digit relay responsive to said key the second time it is actuated. 65
60. In an operator's sender, a digit key, a digit relay, a circuit for said relay completed responsive to the actuation of said key, a transfer relay energized responsive to the opening of said circuit, a second digit relay, and a circuit for said second digit relay placed under the control of said key by said transfer relay. 70

61. In an operator's sender, a digit key, digit storage relays energized successively responsive to successive actuations of said key, and transfer relays energized successively responsive to successive restorations of said key to render the digit relays responsive as set forth. 5
62. In a multi-digit storage, device, a plurality of storage relay sets, a single set of actuating conductors, and means for actuating any relay in a storage set over the corresponding conductor and for thereupon transferring said conductors to the next storage relay set. 10
63. In a registering device, a plurality of sets of storage relays, a single set of actuating keys, means responsive to any key being actuated and released for transferring the control of said key to the next relay 15 storage set, and means also responsive to the actuation of any key for operating the corresponding relay in the instant connected set. 20
64. In a multi-digit register, a plurality of storage relay sets, a plurality of control conductors, means for connecting said conductors to said storage relay sets consecutively, and means controlled over said conductors for setting any relay storage set to 25 which they are connected to store a digit. 30
65. In a counting relay arrangement in which relays are operated in successive stages, a plurality of relays representing each stage, means for selectively controlling 35 the relays of the first stage, and means common to the relays of the first stage for transferring the control to the next stage. 40
66. In a counting relay arrangement in which the relays are operated in successive stages, separately-operable relays representing each of certain stages, and a single transfer-control circuit at each of said certain stages. 45
67. In a telephone system, a plurality of operators' positions, each of which is provided with a single set of ten numerical keys, a plurality of register senders common to said operators' positions, each register sender including a plurality of registers comprising a plurality of groups of relays of various degrees of electromagnetic sensitivity, means for associating an idle register sender with the key set of an operator's position, and switching means individually to 50 each register whereby the repeated operation of a key set is effective to operate a different register of the associated register sender. 55
68. In a telephone system, a plurality of operators' positions, each of which is provided with a single set of ten numerical keys, a plurality of register senders common to said operators' positions, each register sender including a plurality of registers comprising a plurality of groups of 60

relays of various degrees of electromagnetic sensitivity, means for associating an idle register sender with the key set of an operator's position, and a plurality of relays, each individual to a different register for placing the registers of a sender in succession under the control of a key set whereby the repeated operation of a key set is effective to operate a different register of the associated sender. 70

In witness whereof, we hereunto subscribe our names this 19th day of July, A. D. 1923.

ALBEN E. LUNDELL.
EDGAR H. CLARK.
